UNITED STATES PATENT OFFICE.

HERBERT M. FRIENDLY, OF CHICAGO, ILLINOIS.

TELEPHONE SYSTEM.

Application filed January 24, 1921, Serial No. 439,459. Renewed October 27, 1926.

The present invention has for its broad objects the facilitating of so-called code-calling in connection with private automatic exchanges. However, as will appear, it may 5 also be applied in various ways to comprehensive exchanges, as well.

The invention in the specific form chosen for the illustration herein contemplates a so-called two-wire common battery automatic 10 telephone system as has been widely used, the present invention necessitating novel departure from equipments heretofore known, in attaining the new objects, while retaining certain operative functions which are 15 known.

Code-calling, as generally practiced and understood, contemplates a plurality of electromagnetic signal gongs or other sounding devices located at various points throughout 20 an establishment. A central code-controlling or code-transmitting device is provided, usually located convenient to the telephone attendant. Various persons connected with the establishment are assigned certain code- 25 calls, consisting of a series of the signals; these signals being made on the said sounding devices, located so that they may be audible from all parts of the establishment. Thus, if it is desired to gain communication 30 with any one of the parties having a code-call and he cannot be reached directly on his telephone, perhaps, the call-attendant will set the code-transmitting device to sound his code-call throughout the establishment. He 35 will then respond in person or where local telephone service is available, call in to the operator from the most convenient telephone. Such a system in general but not interlinked with a telephone system is set 40 forth in U. S. Letters Patent to Thompson No. 1,199,023, granted September 19, 1916.

Another adaptation of the so-called code-calling has been employed solely as an adjunct to private automatic exchange 45 equipments, wherein the installation of such equipment includes devices, whereby any person at a telephone may call a predetermined telephone number (by dial) and thereafter annex a designated number referring to the code-call of a desired party, whereupon the code-calling will be automatically sounded throughout the establishment in a manner generally similar to that contemplated in the said cited patent, wherein the code-transmitting device is set manually by an attendant.

Where the code-transmitting device has been set functioning by a calling party dialing as hereinbefore referred to, said calling party has been obliged to hold the telephone 60 receiver off the switch-hook awaiting the response of the called party. The called party upon hearing his code-call removes the receiver from the switch-hook of the most convenient telephone and dials a predetermined 65 number, whereupon he gains connection with the first said pre-determined line, held by the calling party.

From the foregoing general description 70 it will be perceived that heretofore code-calling has had two forms; one manually controlled by an attendant, and the other automatically controlled by the calling party from his telephone.

The present invention, among other objects, contemplates organizing in one system equipments having the advantages accruing to the two said general types of code-call equipments. That is to say, an attendant may transmit the code-call by suitably setting the code-transmitting device, or any party may transmit the code-call, controlled by dial from his telephone; the same code-transmitting equipment being employed under either condition.

In carrying out such a plan of operation, as contemplated herein, it is, of course, essential from an operating viewpoint to prevent interference between those desiring to transmit a code-call, for it must be borne 90 in mind that all users will operate independently and without knowledge of the other.

A condition presents itself under the contemplated plan of operation wherein the called party, upon hearing his code-call will 95 not know whether he is sought by the attendant or sought directly from one of the telephones in the system. However, as will appear presently, provision is made so that the party responding to a code-call will, 100 upon removing the telephone from the switch-hook of a convenient telephone, always call a predetermined telephone number, which as will appear (in the present exemplified system), will be telephone number "28" whereupon if the code-call had been transmitted by a manual setting of the code-transmitting equipment by the attendant, the receiving telephone at the attendant's cabinet will be rung and the attendant may 105 then either answer the code-called party in the usual manner by removing the receiver

from the switch-hook, or if the attendant has switchboard equipment may respond by inserting an answering switching-plug into a spring-jack connected to the said receiving telephone. However, had the code-call been initiated by a party at one of the exchange telephones calling the predetermined number (which in the present exemplified system, will appear as number "39"), and thereafter annex the number indexing the code-call for the desired party, upon the latter party responding as before by calling telephone number "28" he will place himself in direct telephonic communication with the calling party at the exchange telephone in lieu of reaching the attendant's receiving telephone. Referring to this function more generally, it may be stated that if the code-call has been initiated by a party calling from a telephone, setting up the code condition through the agency of one of a plurality of code-connectors, the responding party upon calling a predetermined responding number from a convenient telephone will be automatically directed to the code connector to which the calling party is connected. If the code calling has been initiated from the attendant's switchboard, and not through a code-connector, the answering party will be automatically directed to the attendant's telephone.

A further novel function contemplated under the present invention, is that which permits the party initiating the code-calling from a telephone to replace his receiver on the switch-hook at any time after initiating the code-calling and before receiving a response from the called party, and upon the code-called party responding by calling telephone number "28", the telephone from which the code calling was initiated will be rung so that the calling party thereat can respond and be in communication with the said called party, who responded first. It is thus manifest that the calling party is not obliged to retain the telephone off the hook awaiting the response (or non-response) of the called party.

Code-calling initiated from a telephone will be sounded not more than a predetermined number of rounds after the calling party initiates the code-calling, provided the calling party hangs up before the predetermined number of rounds has transpired, and not more than the pre-determined number of times after the calling party hangs up, if no response from the called party is obtained. This is to prevent an indefinite number of rounds of the code, which may be annoying if no response by the called party is obtained. However, the calling party can terminate the sounding of the code-call at any time by momentarily removing the telephone from the switch-hook after he has replaced it. The latter function, provided

a response has not been obtained from the called party, will restore the calling party's telephone line (and interlinked switches) to normal condition forthwith and, therefore, ready for normal outgoing or incoming service.

Heretofore, so far as I am aware, when a code-call has been initiated, controlled from a telephone and has been responded to, no other code-call could be transmitted until after the code-call transmitting equipments have been released by both the calling and the called party terminating the service by "hanging up".

The present invention provides that as soon as the called party has responded, or that the rounds of the code have been terminated as hereinbefore referred to by the calling party again removing his receiver from the switch-hook, before a response has been obtained, the code-equipment is available to others who may desire to use it after the code-transmitting device thereupon restores to normal, as will appear. The present exemplified system contemplates that two parties calling from telephones may hold conversations with parties called by code while the attendant may be transmitting a code-call and receive a response from a third code-calling.

The system contemplated in the present invention, of course, provides for guarding the code-calling equipments against seizure while a code-call is being transmitted and also while the code-transmitting device is in an off-normal state to prevent possible confusion, and under such conditions, an attempt to initiate a code-call will result in the calling party attempting to initiate such code-call receiving the usual busy condition signal.

Referring to the accompanying drawings:

Fig. 1 shows a calling telephone leading to a preselector in access to a plurality of connectors, one only of which is shown.

Fig. 2 is an abbreviated schematic representation of an equipment like Fig. 1, which attaches above Fig. 1 so the lines running towards the margins register.

Fig. 3 is a code-connector, which attaches to the right of Fig. 2, so the lines extending towards the margins register.

Fig. 4 is a code-connector, being a slight modification of Fig. 3, and co-operates with it, and which attaches to the right of Fig. 1 and below Fig. 3, so the lines extending towards the margins register.

Fig. 5 which attaches to the right of Fig. 3 so the lines extending towards the margins register, is a schematic representation of the code transmitting equipments adapted to be controlled by Figs. 1, 2, 3 and 4.

To simplify the drawings and descriptions, the battery (which has its negative pole grounded) and ground are shown as in-

dependent sources throughout, wherever applied, but it is to be understood that the system is of the common battery type. In the descriptions, when a circuit is traced to a 5 winding, the opposite terminals of which is shown applied to grounded battery or to ground, the described circuit is to be considered as traced to ground through the winding and battery or direct to ground, as 10 indicated.

Referring again to the various figures:

In Fig. 1 the calling telephone T (of which there are a plurality in the system) is of the usual series type, having a sending 15 device of the general class, as shown in British patent to Dicker, No. 29,654 of 1910. The pre-selector (also called a lineswitch) PS is of the general class, as shown in U. S. patent to Lamb, No. 1,193,160, granted August 1, 1916. The connector A is of the general class as set forth in U. S. Letters Patent to Deakin No. 1,164,479, granted December 14, 1915. However, the connector 20 designated A of the present invention contains new objects along with those well known. The said connector A is arranged for discriminating service, the telephone line leading from pre-selector PS to telephone T being non-restricted. The set of off-normal contacts 3 is adjusted to close upon the shaft reaching the 10th level, and bank contact positions "28" and "29", and bank contact position "39" and beyond (on the same level). The set of off-normal contacts 4 is 25 adjusted to close upon the shaft reaching the 9th level and bank contact positions "28" and "29", and bank contact position "39" and beyond. The set of off-normal contacts 5 is adjusted to close upon the shaft 30 reaching bank contact position "28" and "29", and bank contact position "39" and beyond. The connector A is designed to function as a selector, the telephonic conductors of which will be clear of battery and ground 35 attachments on the 10th level and also at bank contact positions 28, 29, 39 and 30; as a selector with battery and ground supplied to the telephonic conductors leading to in and out lines supplied through the front- 40 bridge and back-bridge relays on the 9th level, and as a connector with battery and ground supplied over the telephonic conductors to in and out lines, through the front and back-bridge relays on all other 45 levels and bank contact positions. Off-normal contacts ON are adjusted to close upon the shaft stepping from normal. The set of springs designated "11th rot" (and which may be termed "eleventh-rotary springs") 50 are designed to operate upon the shaft moving beyond the 10th rotary position at any level.

It is usual to have a connector of types as heretofore used to cooperate with bank contacts of which there are 10 sets or rotary

positions per level and of which there are 10 levels. The contacts shown at the right of Fig. 1 are assumed to be the last three sets of contacts of the 1st, 2nd and 3rd levels of such a group of levels, respectively. 70

In Fig. 2 the calling telephone T2 is similar to telephone T in Fig. 1. The pre-selector PS2 is similar to PS in Fig. 1. However, the one point of dissimilarity in Figs. 1 and 2 is that the line leading from telephone T2 is restricted against obtaining service on the "O" level. This is by virtue of the contact 6 of the cut-off relay of the pre-selector PS2 being ungrounded. The dotted square designated "A2" represents a 80 connector like the connector A shown in Fig. 1. The bank contacts shown in Fig. 2 are in multiple relation to contacts in Fig. 1 corresponding in position. There would usually be a number of connectors similar to A having their respective bank contacts in multiple relation. 85

The connector Fig. 3 belongs to the general class, as shown in U. S. Letters Patent to Keith & Erickson No. 815,176, granted March 13, 1906, of course, modified in mechanical and circuit details to operate on the well known so-called two-wire principle and to embody the present invention. A salient feature of novelty in this connector 90 is the fact that it is permanently related to an outgoing line and that it has a set of wipers which are adapted to cooperate with sets of bank contacts of the stated type, but that these contacts are wired in such disposition that they will control a code-transmitting mechanism as shown schematically in Fig. 5 and which will be detailed presently. The bank contacts shown may be assumed to be the first four sets of the first 95 level, it being understood, of course, that usually there would be perhaps ten sets of contacts per level and that there would be perhaps ten levels. Thus, in the exemplified instance, provision is made for but four 100 codes, in order not to unduly complicate the drawings and descriptions. It will be manifest to those conversant with the art, and in view of the disclosure, as will appear hereinafter, and the cited patent to Thompson, 105 that a greater number of codes than exemplified may be readily applied by adding more sets of contacts to the level and by employing contacts on a plurality of levels. 110

It will appear presently (and as heretofore adverted to) that the code-connector Fig. 3 includes the function of not only ringing upon its leading-out line, but also will ring back upon its leading-in line, as 115 well as other novel features, as will appear.

In Fig. 5, 501 is a rotatable contact-arm, shown as 20 in the cited patent to Thompson, and is adapted to rotate to the right, successively engaging contacts 502 to 506 (inclusive) and then reengaging the said 120 125 130

contacts in the given order. Off-normal spring set ON5 is arranged to close its two pairs of contacts at all off-normal positions of the arm 501 (shown in normal position), bearing in mind that the arm 501 is designated to rotate completely a plurality of times.

Contact plates 507 to 512 correspond to the plates shown in Fig. 9 of the cited patent to Thompson and fully described therein. However, the wiring disposition of the plates is changed to conform to the present invention. Sufficient to example here that if conducting plug 513 is inserted into the first position indicated by dotted line 514, plates 507, 508 and 512 will be electrically joined, and plates 509, 510 and 511 will be free so far as plug 513 and plates 507, 508 and 512 are concerned. Should plug 513 be inserted into the third position indicated by dotted line 515, plates 507, 508, 510, 511 and 512 will be electrically joined, and plate 509 will be free with reference to these latter plates.

25 Ge represents a direct current supply source and M represents a motor designed to drive the arm 501. 516 and 517 are bells or electromagnetic gongs susceptible to the current projected from the source Ge. 30 Usually there will be a larger plurality of such bells located at various parts of the establishment. At the upper right hand corner of Fig. 5 is a step-by-step mechanism S carrying a grounded wiper 521 which engages the contacts 522 to 526 successively, driven by the magnet D5; the latter magnet, operating ratchet-pawl 527, steps the wiper 521, which is rigidly attached to ratchet wheel 528, one step for each energization of 40 said D5. Retaining-pawl 529 pivoted at 530 is tensioned against the edge of the ratchet-wheel 528. A spiral spring (not shown) has one of its ends secured to the mounting frame of D5 and one of its ends to the 45 ratchet wheel 528, so that when the retaining pawl 529 is attached by release magnet Re5 the wiper 521 and attached ratchet-wheel 528 will be returned to normal. A spiral spring for restoring a shaft to its 50 normal rotary position is shown in the cited patent to Keith and Erickson. Off-normal springs ON5 engage at all off-normal positions of wiper 521.

55 Lamps 531 to 534 correspond to the plug positions indicated by the dotted lines 514, 515, 535, and 536, as also do lamps 537 to 540 as will be manifest presently. The lamps 531 to 534 are controlled by connector Fig. 3, and, glowing designate the engaged 60 position of the wipers of the said connector. The lamps 537 to 540 are controlled by Fig. 4, and, glowing designate the engaged positions of the wipers of the said connector.

65 The operation of the system contemplated under the present invention will be clearly

understood from the following description of its operation under the several assumed conditions.

It is to be understood that the connector A in Fig. 1 (and similarly A2 in Fig. 2, and other similar connectors not shown but which will be referred to) has access to a plurality of exchange telephones, as for example, T and T2, through bank contacts 12, 13, and 14 to telephone T, and 15, 16 and 17 to telephone T2. This is in addition to the auxiliary feature of the code-call, which auxiliary feature forms one of the salient features of the present invention. For that reason the operation of the connectors shown in Figs. 1 and 2 will not be detailed in connection with local telephones under ordinary exchange service conditions, nor with their operation in obtaining access to trunk lines on the 9th and 10th levels whereat the 75 connectors will respectively function as a selector, as contemplated in the cited patent to Deakin. However, it is to be borne in mind that the connectors function somewhat differently as a selector on the 9th level than 80 on the 10th level, in that the battery is supplied from the back bridge relay (E) of the connector to the line wipers 18 and 19 (in connector A) when the switch is functioning on the 9th level, and that this battery is not so applied when the switch is 85 functioning on the 10th level.

90 Assume that party at telephone T desires to summons the party having code-call of three strokes of the gongs, as shall be hereinafter referred to as three bells. Upon removing the receiver from the switch-hook to initiate the call the pre-selector PS will 95 seize the trunk leading to the idle connector A. A circuit may now be traced from battery, upper winding of relay N, conductor 100 20, spring 21, conductor 22, pre-selector wiper 23, conductor 24, through the telephone T, conductor 25, preselector wiper 26, conductor 27, contact 28, conductor 29, lower 105 winding of relay N to ground. Relay N will actuate, applying ground from armature 32, armature 34, contact 35 to winding of slow-releasing relay B, causing relay B to 110 actuate. Ground on contact 30 will be applied through armature 31 to conductor 33 and to the winding of the actuated cut-off relay of the pre-selector PS, thus 115 maintaining it actuated in the well-known manner. The calling party will operate the calling device 2, transmitting digits "3-9-1-3". The transmitting of the first digit "3" effectuates three open impulses, causing relay N to deactuate and reactivate three times, transmitting ground impulses from armature 34, 120 contact 36, side-switch wiper 37, winding of slow releasing relay C through vertical magnet V and through side-switch wiper 38 to battery. This will cause the shaft of the connector to be raised three vertical steps, 125 130

its wipers registering in line with the third levels of bank contacts. Consequent to the first of three current impulses traversing the winding of relay C, its grounded armature 39 will engage contact 40 and energize the private magnet P, causing it to actuate and so remain throughout the series. Upon the cessation of the series of the three impulses relay C deactuates its period thereafter and allows the armature of the private magnet P to retract and permit the side-switch wipers 37, 38 and 41 to advance into their second positions respectively. Upon the second digit "9" being transmitted, constituted of nine open impulses, the described functioning of relays N and C and the private magnet will again ensue. However, due to the side-switch wiper 38 now being in the second position, the described circuit 20 path through relay C to conductor 42 will be continued through armature 43, conductor 44, winding of rotary magnet R, side-switch wiper 38 to battery. The rotary magnet will operate nine times responsive to the said current impulses and rotate the shaft carrying the wipers 19, 18 and 45 into engagement with bank contacts 46, 47 and 48 respectively. A well known mechanical connection exists between the armature of 30 rotary magnet R and the armature of private magnet P, whereby each attraction of the armature of the rotary magnet causes the armature of the private magnet to be moved as if it were acting under normal energization of the private magnet.

Assume that contact 48 constituted battery potential and, therefore, its companion contacts 46 and 47 and attachments are non-busy and seizable, and bearing in mind that 40 upon the retraction of armature 39 of relay C following the last impulse of digit "9" the private magnet deenergized and its armature retracted and permitted the advancement of side-switch wipers 37, 38 and 41 to their respective third positions, a circuit can now be traced from battery through the resistance 302, conductor 301, conductor 201, bank contact 48, wiper 45, side-switch wiper 41, inside-winding of relay H, contact 49 of 50 private magnet, conductor 50, conductor 51, upper armature of relay B, wiper 52 of pre-selector to grounded contact 53 on the cut-off relay in the pre-selector. The relay H will actuate, and will lock as will be herein-after detailed.

In this connection it is to be borne in mind that under the assumed operative condition, off-normal contact sets 3, 4, and 5 are operated. Thus, a circuit will ensue 60 from battery through relay D to ground on spring 54, and a supplemental ground will also be applied to conductor 51 through off-normal set 5 by way of upper armature of relay B. However, had the station T (like T2) been a restricted station, denied access

to lines on the 10th level, there would be no ground on cut-off relay contact 53 in the preselector PS and therefore, the supplemental ground will be operatively applied to conductor 51 through off normal set 5. Relay H will actuate energized over the described circuit. It is manifest that had wiper 45 not found battery potential on bank contact 48, an energization circuit for relay H would not have been established after the side-switch wipers 37, 38 and 41 moved into their respective third positions, and the relay H would, therefore, remain inert. Under the latter condition a circuit would be established from ground on contact 30 of relay B (relay B being actuated) armature 31, conductor 33, contact 57 on relay H, conductor 58, side-switch wiper 37, winding of relay C, outside winding of relay J, side-switch wiper 38 to battery. Relay J will 70 actuate and remove ground from armature 34, thus preventing movement of the switch shaft should the sending device 2 be manipulated. Relay H being normal, no telephonic circuit will be established to the wipers 19 and 18.

Had bank contact 48 constituted ground potential by reason of one of its multiples, as 59, being in a seized condition by wiper 60 of an assessable connector, A2 for example, when the wiper 45 engaged it and after relay C deactuated, a circuit path would be established from said grounded contact 48, wiper 45, side-switch wiper 41 (in second position) armature 61, contact spring 40, conductor 62, winding of private magnet P, causing said P to remain energized, thus preventing the said side-switch wipers from moving into their respective third positions. Relay J now being normal, due to the side-switch wiper 38 being in its second position, and the rotary magnet being unenergized, a circuit can be traced from winding of the rotary magnet, conductor 44, contact 63 to grounded armature 32. The rotary magnet 90 will actuate and advance the shaft one rotary step so wiper 45 will engage with bank contact 64 (corresponding to code-connector Fig. 4 as will appear presently), relay J actuating through the rotary magnet auxiliary contacts 65 and off-normal set 4, thus opening the rotary magnet energizing circuit, and allowing the rotary magnet to deenergize and restore, followed by dependent relay J, whereupon the circuits are in the condition as in the exemplified instance when wiper 45 engaged bank contact 48 after relay C deactuated.

Assume further that bank contact 64 also constituted ground potential (the selector shown in Fig. 4 being engaged) then the same circuit condition will assume as when relay C deactuated after wiper 45 engaged bank contact 48, when assumed as constituting ground potential, so the rotary magnet 110 120 125 130

will again function and drive the shaft a rotary step, a shaft-cam engaging and operating the 11th rotary cam-spring set.

The wipers, 19, 18 and 45 being now free of the bank contacts, after relay C deactuates, an inert circuit path can be traced from battery through resistance 65, conductor 67', side-switch wiper 41 (in second position), armature 61, contact-spring 40, conductor 62, winding of private magnet P to battery. The private magnet will thus not be energized now and will retract, following the deactuation of relay C, allowing the side-switch wipers 37, 38 and 41 to advance into their respective third positions, whereupon the battery traced through resistance 65 to side-switch wiper 41 will be applied through inside winding of relay H, contact 49, conductor 50, upper armature of relay B, off-normal contact set 5 (also to grounded contact 53) to ground, causing said relay H to actuate and lock its outside winding through contact 66, armature 67, conductor 33, armature 31, to grounded contact 30. A circuit can forthwith be traced, before relay B can deactuate, as relay K will actuate because of the establishing of a circuit from its winding through off-normal contact set 3, conductor 70, contact 71, contact 72, armature 67, conductor 33, armature 31, to grounded contact 30. Also, a circuit can forthwith be traced (before relay B can deactuate, as will appear) from battery through resistance 73, conductor 74, winding of relay G (and its shunt), armature 75, conductor 76, contact-spring 21, over the described path through the telephone set T to armature 77, conductor 78, contact 79, to grounded resistance 81. Relay G being operatively energized over this circuit path, causes a ground to be applied to the winding of relay B from grounded armature 82 and conductor 83 (before relay B has had time to deactuate due to its primary relay N deactuating because of being disassociated from conductors 22 and 27 consequent to the described actuation of relay K), maintaining ground on conductor 33 through armature 31 and contact 30.

Ground-seeking tone-source TS is applied to the free side of resistance 81 and will convey an audible tone to the calling party holding telephone T, over the described path including resistance 73. The calling party being thus apprised that both the code-connectors Fig. 3 and Fig. 4 are busy, will replace the receiver on the switch-hook and terminate the service, whereupon relay G will deenergize and deactuate, followed by dependent relays B, H and K. An operative circuit will now ensue from the lowermost armature of relay H, winding of the release magnet Re, off-normal contact spring 84, armature 85, armature 34, to grounded armature 32. Upon the release magnet Re operating the switch shaft will be restored to

normal, and relay D will be deenergized and restore.

Going back to the assumed condition of bank contact 48 constituting battery potential (as it does normally) when first engaged by wiper 45 and after relay H actuated, a locking circuit is formed from outside winding of relay H, contact 66, armature 67, conductor 33, armature 31, to grounded contact 30. Also, ground on armature 67 is applied to contact 86 through side-switch wiper 41, wiper 45, bank contact 48, conductor 201, conductor 301 to the free terminal of resistance 302. Thus, the battery potential primarily existing, upon bank contact 48 and bank contact 59 (and its multiples) is changed to ground potential, guarding them from subsequent seizure by an accessible connector as A2, for example.

A circuit may now be traced from the upper winding of relay 303, conductor 304, conductor 305, contact spring 306, conductor 307, armature 308, conductor 309, conductor 202, bank contact 47, wiper 18 winding of shunted relay G, armature 75, conductor 76, contact spring 21, over the described circuit path including telephone T to armature 77, conductor 78, contact 79, wiper 19, bank contact 46, conductor 90, conductor 91, contact 311, contact 312, conductor 313, conductor 314 to the lower winding of relay 303. Relay 303 will actuate applying grounded armature 315 to contact 316 and to the winding of slow-releasing relay 317, causing it to actuate.

Upon the calling party sending the third digit "1" by manipulating the sending device 2, in accordance therewith, the circuit including the windings of relay 303 will be opened one time, causing armature 315 to retract against contact 318, and apply ground to contact 319, conductor 320, armature 321, conductor 322, winding of slow-releasing relay 323, winding of vertical magnet V3, side-switch wiper 324, to battery, causing the said vertical magnet to actuate and move the shaft of the code-connector Fig. 3 one vertical step. When relay 323 was energized its grounded armature 325 applied ground to the winding of private magnet P3, causing it to attract its armature. Upon the deactuation of relay 323, its period after the cessation of the current energizing the vertical magnet, the private magnet is deenergized, allowing its armature to retract, permitting the side-switch wipers 324 and 326 to advance into their respective second positions. Upon the party at the calling telephone transmitting the fourth digit "3" by manipulating the sending device 2 in accordance therewith, relay 303 will deactuate and reactuate three times responsive to the series of three impulses constituting the digit "3", applying three grounded impulses over the before described circuit path from grounded ar-

mature 315 through the winding of relay 323. However, this time to the winding of the rotary magnet R3, side-switch wiper 324 to battery, causing the rotary magnet (and relay 323 to attract as before) to operate three times and rotate the shaft carrying wipers 327 to 331 three rotary steps and into engagement with bank contacts 332 to 336 respectively. Upon the cessation of the said series of three impulses through the winding of relay 323 and its armature retracting, causing the private magnet to in turn retract permitting the side-switch wipers 324 and 326 to advance into their respective third positions, a circuit path as follows will ensue: battery on side-switch wiper 324, conductor 337, winding of relay 338, side-switch wiper 326 to ground, causing relay 338 to actuate. Grounded armature 339 will apply ground to wiper 331 and its engaged bank contact 336, conductor 340, through lamp 533, to battery, causing the said lamp to glow, indicating to the attendant that code-connector Fig. 3 is transmitting a code-call and that the code-call being transmitted is three bells as indicated by the glowing of the said lamp 533. Grounded armature 341 applies ground to contact 342 and to the winding of relay 343 causing it to actuate. A circuit may now be traced from conductor 344 to wipers 327 to 330. Grounded armature 345 applies ground to contact 346, conductor 347 and to the winding of relay 541, causing it to actuate. Bearing in mind that the plus pole of current source Ge is common to the plus terminal of the motor M, a circuit may now be traced from the minus pole of current source Ge, conductor 542, armature 543, conductor 344 and its attached wipers 327 to 330 in engagement with bank contacts 323 to 335 respectively. A circuit may also be traced from armature 543 over conductor 544, contact 545, to the minus terminal of motor M. This will cause motor M to be energized and start its rotation, and remembering that the motor drives the contact arm 501, and that the said arm upon starting its rotation successively engages contacts 502 to 506, and that upon the off-normal movement of arm 501 the sets of contacts constituting off-normal set ON5 engage respectively, a circuit may be traced from the plus pole of supply source Ge through winding of relay 546 to arm 501. From the fact that the wipers 327 to 330 are engaged to bank contacts 332 to 335 respectively a circuit path exists from the minus pole of the supply source Ge over conductor 542, armature 543, conductor 344, wiper 329, bank contact 334, conductor 348 to contact 503. Also, from conductor 344, wiper 328 bank contact 333 conductor 349 to contact 504. Also from conductor 344, wiper 327, bank contact 332, conductor 350 to contact 505. Thus, as arm 501 in its rotation successively engages the

bank contacts 503 to 505, it will complete a circuit from the minus pole of the supply source Ge through the arm 501, winding of relay 546 to the plus pole of the said supply source. Each time this circuit is completed 70 the relay 546 will become energized and close a circuit from the minus pole of supply source Ge over conductor 547, through the windings of the gongs 516 and 517 in multiple to conductor 548, armature 549 to conductor 550 and to the plus pole of the supply source Ge. The gongs will sound responsive to each of the three actuations of relay 546, consequent to the arm 501 engaging the contacts 503 to 505. It is to be borne 80 in mind that bank contact 335 is free and that there is no continuity between contact 502 and conductor 344.

As arm 501 engages contact 506 following the disengagement of the last code operative 85 contact 505, a circuit may be traced from the minus pole of the supply source Ge over conductor 547, through the drive magnet D5, conductor 551, armature 552, conductor 553, contact 506, arm 501, winding of relay 546, 90 conductor 550 to the plus pole of the supply source Ge, causing the drive magnet D5 to attract resultant thereto and step the wiper 521 into engagement with dead bank contact 522. Consequent to the energization of the 95 latter described circuit, relay 546 will close the described circuit including the windings of the gongs 516 and 517. Contact 506 being located very close to bank contact 505 will cause the last bell of the code series to 100 be followed by a supplemental stroke at a very short interval thereafter, indicating to the auditors that the end of the code has transpired, and therefore, it will not be confusing where codes may consist of different- 105 ly spaced strokes of the gongs.

Assume no response will be made by the called party, the arm 501 will continue rotating and successively engage the contacts 502 to 506 until five impulses have been imparted over the described path, including conductor 553, and therefore, the drive magnet D5 has caused the wiper 521 to engage the fifth bank contact 526. A circuit may be traced from grounded wiper 521, bank contact 526, conductor 554 to the winding of release magnet Re5, causing said release magnet to actuate, attracting the retaining pawl 529 from ratchet-wheel 528, causing the latter and its attached wiper 521 to restore to normal due to the influence of the retractile spring shown attached to the ratchet wheel. 115

At the time release magnet Re5 is energized multiplied relay 555 is energized and actuated. The purpose of this said relay will be detailed presently. Due to the fact that relay 541 is only energized from one of the connectors, as Fig. 3 or Fig. 4, (and not through the agency of plug 513) as will be 125 manifest presently, armature 552 will not 130

be disengaged from its resting contact 556 under the conditions wherein the code transmitting device is controlled by the attendant through the agency of plug 513, (as relay 541 will be normal) and therefore, there will be no limit to the number of rounds of the code-calling which can ensue while manually controlled and supervised by the attendant. Under the latter condition, that of the code-calling being initiated by the attendant, relay 541 being normal, drive magnet D5 will be excluded from the operative circuits, the traced circuit path from conductor 553 now being diverted at armature 552 to resting contact 556, conductor 557 to conductor 547. Thus, the drive magnet D5 will only operate when relay 541, controlled by a code-connector, is actuated.

It has been set forth that conductor 301 becomes grounded from connector A (or A2) at the time code-connector Fig. 3 is seized. A circuit can therefore be traced from grounded conductor 301, contact 352, conductor 353, contact 558, to the winding 25 of slow-releasing relay 559, causing it to actuate, disassociating plates 507 to 512.

At the time arm 501 is moved off-normal, operating off-normal set ON5, a circuit may be traced from conductor 542 through the 30 lower set of springs of off-normal set ON5 to the minus terminal of motor M. It will thus be clear that the terminals of motor M are thus connected to the corresponding poles of the supply source Ge, independent of the 35 closure of the described circuit from conductor 542, armature 543, conductor 544, contact 545 to the minus terminal of motor M, by reason of the actuation of relay 541 at the time relay 343 actuated. It will be clear 40 presently that should any condition arise whereby relay 343 would deactivate, as for example, by the calling party causing the code-connector Fig. 3 to be restored to normal, forthwith causing the relay 541 to deactivate and open the motor-start circuit including conductor 544, as described, the motor will continue revolving until wiper 501 reaches its normal position, wherein the 45 lower set of springs of off-normal set ON5 will disengage and open the motor circuit. That is to any, complete rotations of the arm 501 only can be effected, even though the primary start motor circuit traced is opened before a complete code-call series has transpired.

It will be assumed, now, that after the operations of code-connector Fig. 3, including the actuation of its relay 343 as described, and further that the code-calling 50 is transpiring, sounding series of three bells, the calling party restores his receiver on the hook-switch, not wishing to await the response of the called party. Relay 303 will deactivate, and its dependent relay 317 applies ground from lower spring of off-nor-

mal set ON3, spring 354, contact 355 to the winding of relay 356, causing it to actuate. A locking circuit for this latter relay will now exist from grounded conductor 301, conductor 357, spring 358, contact 359 to 70 the winding of said relay 356. Under the present condition conductor 301 still receives ground from over the described path in connector A, and also from armature 359 in the code-connector Fig. 3, by way of spring 75 358, and conductor 357. However, due to the energized path described as including the calling telephone T and the relay G becoming open consequent upon the calling party replacing the receiver on the switch-hook at telephone T, the said relay G (which is slow-releasing, due to the shunt winding thereon) will deactivate and remove ground from the winding of relay B, causing the latter relay to deactivate its period 80 thereafter. Ground on contact 30 is disassociated from conductor 33 due to the retraction of armature 31 of relay B. Remembering that conductor 301 constitutes ground potential applied from lower spring 85 of off-normal set ON3, and that relay H was actuated and locked at the time armature 31 retracted, it will be clear the latter relay will be maintained locked from the ground received from the conductor 301 by 90 way of contacts 86 and 66. While a circuit can now be traced from the grounded armature 32, armature 34, armature 85, off-normal spring 84 to the winding of the release magnet Re, the battery normally on its lower terminal is disassociated at the lowermost armature of attracted relay H, and therefore the connector A is incapacitated 95 against releasing. That is to say, if the leading-in test conductor 301 of code-connector Fig. 3 constitutes ground potential applied from within code-connector Fig. 3, when the calling party restores the receiver on the switch-hook at telephone T, the connector A cannot release and the telephonic circuit previously established to the leading-in line conductors of the code-connector 100 Fig. 3 is maintained.

It will now be assumed that no response by the called party will be made. Then, upon arm 501 engaging contact 506 for the fifth time at the end of the fifth round, wiper 521 will engage bank contact 526 and complete a circuit to the winding of the release magnet Re5, causing the wiper 521 and its attached ratchet-wheel 528 to be retracted to normal, and relay 555 to be momentarily actuated as has been set forth hereinbefore. A circuit can then be traced from the winding of the release magnet Re3, spring 360, armature 361, contact 362, conductor 363, grounded contact 560, causing the release magnet Re3 to actuate and restore the code-connector Fig. 3 to normal.

The described circuit, including the wind-

ing of relay 303, includes contact set 367 on the release magnet Re3, therefore, the circuit, including the windings of relay 303 will be opened by the actuation of the release magnet Re3 in restoring the connector Fig. 3. The purpose of this will appear presently. A locking circuit for the release magnet Re3 will be closed from release magnet armature 368, spring 358, contact 359. 10 contact 355, spring 354 to engaged grounded spring, and to conductor 301. Therefore, the release magnet upon actuating will become locked actuated until the said ground path is opened at spring 354. It will be remembered that under the now assumed condition, no ground is applied to conductor 301 from connector A, and in fact, relay H is maintained from ground received from spring 354. It is now manifest that upon 15 the shaft of the code connector Fig. 3 restoring, not only will the release magnet Re3 restore, but also relays 356, 338, and 343, as well as relay H in connector A, whereupon the described path to the release magnet Re will be continued to battery on the lowermost armature of relay H, causing the restoration to normal of connector A.

Had the calling party not restored the receiver on the switch-hook, and five rounds of code-calls were allowed to transpire while he held the receiver off the switch-hook, awaiting the response of the called party, the restoring functioning of ratchet-wheel 528 when wiper 521 engages bank contact 526, and also the actuation of relay 555 would, as set forth, be coincident with the actuation of the release magnet Re5. However, the code-connector Fig. 3 would not be restored because armature 361 would be at normal, and therefore, no ground circuit from the winding of the release magnet Re3 over the described path to grounded contact 560 would be established. If the calling party would after the said release of ratchet-wheel 528, at the end of the fifth round restore his receiver on the switch-hook, armature 361 of relay 356 would attract as before described and prepare the described releasing circuit to energize the release magnet Re3 at the termination of the second five rounds of bells.

Assume now, that while the code bells were being sounded the calling party for some reason wished to stop the code calling, bearing in mind that upon hanging up the receiver on the switch-hook after initiating the code-calling, relay 303 and 317 deenergized and restored in sequence and that relay 356 actuated and locked. He would remove his receiver from the switch-hook (having previously replaced it upon the switch-hook after initiating the code-calling) which would cause relay 303 to energize and actuate, followed by relay 317.

The winding of relay G being in series with the windings of relay 303 it will energize and armature 82 will apply ground to the winding of relay B, so the condition in connector A is now as described upon its seizure of code-connector Fig. 3. However, as will appear, this condition endures for but a brief operative period.

A circuit can now be traced from the winding of release magnet Re3, spring 360, 75 armature 361, armature 364, to grounded armature 365, causing the release magnet Re3 to actuate and restore the code-connector Fig. 3 to normal. This restoration to normal will, of course, imply the deactivation of its actuated relays and the disassociation of its wipers 327 to 331 from engaged bank contacts, and also the deactivation of dependent relays in Fig. 5.

It has been set forth that the energizing circuit including the winding of relay G and the windings of relay 303 will be opened consequent to the release magnet Re3 actuating and attracting armature 367. Also, that the ground path from conductor 301 in code connector Fig. 3 will become opened consequent thereto. Under the stated condition relay G will deactivate and dependent relay B will deactivate, removing ground from conductor 33. Relay H 95 will deactivate. Relays N, B, J and H being now normal, the described releasing circuit including the release magnet Re will be completed and the connector A will be thereby released to normal. Upon the shaft 100 of connector A retracting from its operated position the circuit described as including relay K will be opened, resulting in said relay K deactivating and establishing the windings of line relay N in circuit with telephone T as described at the outlet, as if the call into connector A were initiated at this time. It is thus clear that while normally connector A will release to normal 105 when the calling party restores the receiver on the switch-hook at telephone T, this functioning is materially changed when the said connector A cooperates with a code connector, as Fig. 3, in that its release to normal now depends upon the release of the code-connector, which as has been fully set forth, does not restore responsive to the receiver at telephone T under the stated condition.

Assume further that at least one complete 120 round of bells have transpired, at the time of last removing the receiver of telephone T, and therefore, arm 501 had engaged contact 506 and caused wiper 521 to be in off-normal position. Then, a circuit can be 125 traced from release magnet Re5, off-normal set ON^t to grounded armature 568, causing the said release magnet to actuate and restore the wiper 521 to normal position. The motor M will cease rotating, following 130

the deactuation of relay 541, as will appear presently.

While relay 546 operates, transmitting code-impulses as described, armature 565 closes an inductive circuit, including resistance 566 and condenser 567 between conductors 369 and 370. Bearing in mind that while the code-call is transpiring and the calling party has the receiver off the switch-hook, relay 338 and other stated relays in Fig. 3 will be actuated, an inductive circuit path will be closed from generator G3, armature 371, contact 372, conductor 373, condenser 567, resistance 566, armature 565, conductor 374, armature 375, contact 376, inside-winding of relay 377 to battery, and from condenser 567 through ringer 567' to conductor 374. The interrupted current from source G3 traversing this circuit path will induce a tracing audible to the calling party, from battery, outside winding of relay 377, lower winding of relay 378, conductor 379, conductor 313, contact 312, contact 311, conductor 91 over the described path, including the telephone T to conductor 309, armature 308, conductor 307, spring 306, conductor 305, conductor 304, upper winding of relay 303 to battery. Thus, for every closure of relay 546, a brief tracing of greater intensity will be audible to the calling party and index that the code-call is transpiring normally. This would be of convenience where the gongs 516 and 517, for example, are located too remote to be audible to the calling party.

Assume that the called party upon hearing his code-call responds from a convenient telephone by removing the receiver from the switch-hook to initiate the call in a normal manner, and further assuming that this telephone is the one shown in Fig. 2 designated T2. The pre-selector PS2 will seize the trunk line leading to the connector represented by A2. The responding party will then manipulate the calling device 203 to operate the connector A2 in a manner as described with relation to telephone T and the connector A shown in Fig. 1 by the calling party at telephone T only in this instance the responding party will effectuate the calling of telephone number "28", (in lieu of telephone number "39") whereupon the wipers 60, 205 and 206 will engage bank contact 207, 208 and 209 respectively.

Going back to the code-connector Fig. 3, it will be noted that normally ground potential exists on conductor 380, by way of contact 381, contact 382 and grounded armature 365, but that when the code-connector Fig. 3 was seized by the connector A in Fig. 1, as described and relay 303 actuated this ground potential normally existing on conductor 380 is changed to battery potential by virtue of a circuit being completed from contact 381, contact 383, through resistance 384 to

battery. It will also be noted that when the calling party replaces the receiver on the switch-hook allowing the code-calling to still transpire as set forth hereinbefore, and relay 303 deactuated and relay 356 actuated ⁷⁰ and locked, the battery potential was maintained on conductor 380 by way of contact 385, resistance 384 to battery. Thus, while the conductor 380 has ground potential on it normally, it has battery potential on it ⁷⁵ when its leading-in conductors are seized by connector A, but it will be clear presently that this is again changed to ground potential incident to the seizure of the leading-out conductors of the code-connector by the ⁸⁰ connector A2, controlled as described by the responding party.

The object of having ground potential normally on conductor 380 is to maintain a guarding or busy condition on the leading-out conductors of the code-connector at bank contact 207 at all times, except when the code-connector is controlling a code-call. It will be manifest presently that this is primarily to constrain the connector as A2, ⁸⁵ operated by the responding party, from seizing bank contacts leading to a code-connector other than the one to which the calling party is connected, and also to insure that neither code-connector can be reached by a responding party if the code-call is under the control of the attendant, set manually.

A circuit can now be traced from the inside winding of relay 377, contact 376, armature 375, conductor 370, conductor 212, bank contact 209, wiper 206 through the connector A2, wiper 213 of pre-selector PS2, line conductor 214, condenser 218 and ringer 219 (218 and 219 shunted by the conductive path through the receiver) of the telephone T2, ¹⁰⁰ line conductor 215, wiper 216 of pre-selector PS2, through the connector A2, wiper 205, bank contact 208, conductor 217, conductor 369, contact 372, armature 371 to generator G3. Relay 377 is designed to be inoperative to the varying current traversing telephone T2 with its receiver on the switch-hook from source G3, but to be operative from direct current, as will traverse the circuit ¹⁰⁵ traced through the calling telephone T2 with its receiver off the switch-hook, and therefore, relay 377 will actuate and lock its outside winding to contact 386, spring 354 to grounded lower spring of off-normal set ON3. This will also apply ground now on conductor 387 to the inside terminal of the lower winding of relay 378. The circuit described from armature 375 through the connector A2 and telephone T2 and back through the connector A2, and armature 371 ¹¹⁰ can now be traced from armature 375, contact 388, conductor 389 and to the upper-winding of relay 378, and from armature 371 to conductor 379, lower winding of relay 378, conductor 387, contact 386, spring 354 ¹¹⁵ to

to ground on the lower spring of off-normal set ON3, causing relay 378 to actuate. It will be manifest that a divided circuit path from conductors 369 and 370 exists including conductor 373, condenser 567, ringer 567' and conductor 374, so the said ringer 567' will operate, of course, periodically shunted by armature 565 and its make contact corresponding with the code bells, as set forth. Obviously, a plurality of ringers as 567' may be similarly connected in multiple relation between conductors 373 and 374. The ringer 567' manifestly supplements the gongs 516 and 517.

In this connection it is manifest that it is not necessary to have a signaling current supply source G3, and that therefore the conductor leading to the upper terminal of G3 may be run direct to ground. The only changed operative effect would be that bell 567' would not be rung and no inductive tracing of the ringing current would be projected to the calling party, though periodic disturbances corresponding with the closure of armature 565 would be discerned.

Returning for a moment to relay 377, which actuated consequent upon connector A2 seizing code-connector Fig. 3 incident to the response of the called party, the ringing current source G3 was disconnected from armature 371. Ground was removed from conductor 353 which allows relay 559 to deactuate, making the code-transmitting equipment available for manual control by the attendant and, as will appear presently, also available to other calling parties who may initiate a code-call from a telephone. By reason of armature 341 attracting, relay 343 will deenergize and deactuate, freeing contacts 503 to 505 from conductor 344, and causing its armature 345 to retract from contact 346 and unground conductor 347 causing relay 541 to deactuate and open the primary-start circuit of the motor M. Should the rotating arm 501 happen to be at its normal angular position at this instant, the lower set of contacts of off-normal set ON5 would be opened, and therefore the supply current to the motor M would be opened and the arm 501 would, therefore stop revolving. However, if the arm 501 were in the process of revolving, in its off-normal position, and that the lower set of contacts of off-normal set ON5 would, therefore, be engaged, the primary-start circuit of the motor would be maintained closed, and this would endure until the arm 501 reached its normal angular position, whereat the said lower set of contacts of off-normal set ON5 would disengage, and open the current supply to the motor M, causing it to cease rotating. The lower armature of relay 377 attracting from its contact 362 prevents any ground coming from grounded contact 560 as might be transmitted by another code-connector, as

code connector shown in Fig. 4 for example, as will appear might, in normal operation, cause relay 555 to actuate, and apply ground to the release magnet Re3 falsely over the path described from grounded contact 560. 70

Assume that at the time relay 378 actuated as described, the calling telephone T was on the switch-hook, it having been replaced there by the calling party, after he initiated the code-calling and the code-calling was, therefore, transpiring, a circuit can now be traced from generator G3', contact 390, contact 311, conductor 91 over the described circuit path to telephone T (the receiver of which is on the switch-hook) 80 through the condenser 92 and the signal bell 93, to the conductor 25 and over the traced circuit to conductor 309, armature 308, conductor 307, contact 306, and its engaged armature, inside winding of relay 391 to battery. The signal bell 93 at the calling telephone T will ring responsive to the signaling current derived over the latter described circuit path. The calling subscriber will respond in the usual manner by removing the receiver from the switch-hook, whereupon the last described circuit will become conductive through the receiver. Relay 391 is so designed that it is inoperative to signaling current of the character emanating from the source G3', but it is susceptible to direct current as will traverse the circuit upon its conductive closure consequent to the removal of the receiver from the switch-hook by the calling party. Relay 391 being now actuated the 100

circuit path from the calling telephone T traced to conductors 91 and 309 may be traced through contact 392, contact set 367, lower winding of relay 303 to ground, and from the free terminal of the upper winding 105 of relay 303, conductor 304, armature 308 to conductor 309. Relay 303 thus energizes and actuates following the actuation of relay 391, which latter transpired consequent to the removal of the receiver from the switch-hook at calling telephone T. A telephonic circuit now exists from the calling telephone T over the described path to conductors 91 and 309, including the responding telephone over the circuit from contact 392, conductor 379, armature 371, contact 372, conductor 369, bank contact 208, wiper 205, over the described path through the responding telephone to wiper 206, bank contact 209, conductor 212, conductor 370, armature 375, 115 armature 376, contact 388, conductor 389, armature 308 to conductor 309.

At the time relay 391 actuated its armature 393 attracted, locking the outside winding through off-normal contact 354 to the lower grounded spring of off-normal set ON3. At the time current was being projected from grounded generator G3' to actuate the bell 93 of the calling telephone T, 125 before relay 391 actuated, wherein the cir- 130

cuit was completed through the inside winding of relay 391 to battery, a tracing, received inductively from the inside winding of relay 391, was audible to the party at the 5 responding telephone T2 over the following circuit path: battery to outside winding of relay 391, armature 393, and its resting contact, condenser 394, resistance 395, conductor 379, over the described path through the re- 10 sponding telephone to conductor 389, through the upper winding of relay 378 to battery, and upper winding of relay 303 to ground from said conductor 389. The said tracing, audible to the responding party, 15 indicates to him that signaling current is being projected to ring the bell 93 at the calling telephone and that he must therefore await a response from a calling party though he himself responded.

20 Assume now that a conversation ensues between the calling and the responding party and that the calling party replaces the receiver on the switch-hook at telephone T while the responding party is still holding 25 his receiver. Relay 303 will deenergize and deactivate, following by relay 317, its period thereafter. Slow-releasing relay 396' is energized consequent to the first off-normal movement of the code-connector Fig. 3, its 30 winding deriving ground through spring 354 and the lowermost armature of relay 317. Due to its slow-release characteristic, relay 396' will remain sustained a period after relay 317 deactuates. A circuit can now be 35 traced from the winding of the release magnet Re3, spring 360, armature 396, armature 397, armature 398 to grounded contact 399. Thus, the path described including contact 399 occurs only if the calling party at tele- 40 phone T has replaced the receiver on the switch-hook and then responded to the called party, at telephone T2, and after the telephonic connection with telephone T2 again replaces the receiver on the switch-hook be- 45 fore the party at telephone T2 replaces his receiver on the switch hook. Were relay 396' and the associated circuits not pro- 50 vided, the release under the last assumed condition would take place only upon the party at telephone T2 replacing his receiver on the switch-hook, whereupon the path from the winding of the release magnet Re3 is established through spring 360, lowermost armature of relay 378 to grounded armature 55 365. The release magnet Re3 will actuate, and remembering that conductor 301 is now grounded dependent upon armature 82, of relay G in connector A, the release magnet Re3 will lock and remain locked until the 60 said ground is removed from conductor 301, as described hereinbefore. At the time the release magnet Re3 actuated, it opened the energizing circuit of relay G at contact set 367, as described hereinbefore. Relay G 65 will therefore deactivate its period after the

said opening, and consequent to armature 82 retracting ground will be removed from conductor 301, unlocking the release magnet Re3. Following the retraction of armature 82, relay B will deactivate, completing an op- 70 erative circuit for the release magnet Re as before described, resulting in the connector A being restored to normal.

It will be assumed that the code-connector Fig. 3 has been seized by connector A as set forth the code-connector is thereafter caused to be stepped-off-normal, but not in a rotary direction, at least not having seized a set of code-bank contacts and that the calling party replaces the receiver on the switch-hook at telephone T. Relay 356 will actuate and lock as before set forth, whereupon a circuit will be established from grounded armature 345, armature 397, armature 396, off-normal spring 360 to the winding of the release mag- 80 net Re3, causing the shaft of code-connector Fig. 3 to be restored to normal and locking the release magnet Re3 as before described until the ground is removed from the test conductor 301 by reason of relay G in connector A deactuating resultant to armature 367 opening its energizing circuit.

Assume that instead of the calling party at telephone T replacing the receiver on the switch-hook, while the responding party at telephone T2 held his receiver, that the responding party at telephone T2 replaced his receiver on the switch-hook while the calling party still retained his off the switch-hook. Upon the responding party opening the de- 90 scribed circuit including the winding of relay 378, resultant to his replacing his receiver on the switch-hook, relay 378 will deactivate, closing a circuit from the winding of release magnet Re3, spring 360, lower ar- 100 mature of relay 378 to grounded armature 365, causing the release magnet Re3 to actuate and lock as before described, restoring the code connector Fig. 3 to normal. Connector A will release to normal as before set 105 forth, consequent to the actuation of the release magnet Re3. Thus it is manifest that while the connector A is held, dependent upon the actuation of the release magnet Re3 in the code connector, the code connector receives its busy ground existing on conductor 301 and bank contact 48 from the connector A. Heretofore in the art so far as I am aware, the controlling switch has applied the busy ground rather than the dependent 115 switch, as in the present invention.

Refer back to the assumed condition wherein the calling party had caused the code-calling to transpire and had there- 120 after, before attaining the response of the called party, replaced the receiver on the switch-hook. It will be assumed now that the called party responds as before set forth, but that the calling party has possibly left his telephone, or in any event, no response 125 130

is made at the calling telephone T to the sounding of its signal bell 93, consequent to the responding party obtaining telephonic connection with outgoing conductors of the 5 code connector Fig. 3 in the manner before detailed. The responding party after a time, replaces the receiver on the switch-hook of telephone T2 and causes connector A and code connector Fig. 3 to be restored to normal as follows: Relay 378 restoring (bearing in mind that relay 391 is normal) a circuit may be traced from the winding of the release magnet Re3, spring 360, armature 396, armature 397, to grounded armature 15 345, it being remembered that armature 345 retracted consequent to relay 377 actuating upon the responding party removing the receiver from the switch-hook of telephone T2. It will be obvious that the release magnet 20 Re3 will actuate followed by the actuation of the release magnet Re of connector A. Consequent to the said restoration of the code-connector Fig. 3 wherein relay 338 deactuates and opens the leading-in path at armature 375 and at contact 372, the path including the winding of the relay in connector A2 corresponding to G in connector A is opened. Thus, connector A2 will be restored in a 25 manner as hereinbefore described with reference to its like connector A.

It will be observed that in view of the code-connector always releasing before its cooperating connector A removes ground from the bank contact engaged by its wiper 35 45 that there will be no lapse of ground potential on conductor 380 and its attached bank contacts incident to a release functioning and that therefore the only times the said attached bank contacts and the said 40 conductor 380 do not constitute ground potential are the conditions set forth wherein relay 356 is actuated, or relay 303 is actuated after the seizure of the leading-in conductors of code connector Fig. 3 by connector A and before connector A2, operated by the responding party seizes the leading-out conductors of the said code-connector 45 Fig. 3.

It is manifest that under the condition of 50 the calling and responding party being in telephonic communication as set forth, all the relays enumerated in Fig. 5 will have restored to normal, bearing in mind, however, that arm 501 may have to complete part 55 of a revolution before attaining its normal angular position at which time the code transmitting device in Fig. 5 is free and is subject to seizure by a co-operating code-connector as Fig. 4, for example, or may be 60 controlled by the manual setting of the code transmitting device through the agency of plug 513 singly or in plurality as has been adverted to.

It will be manifest that as long as the 65 code-connector Fig. 3 is in engagement with

a set of bank contacts, 332 to 336 exemplified herein, lamp 533 will glow, and that the attendant will, therefore, know that the code transmitting equipment is out of her control and that the indexed code-connector is in 70 control of the code-transmitting device and that the specific code-call indicated by the particular lamp is transpiring.

It was stated at the outset that a greater plurality of connectors, such as A and A2, 75 were in common access to the code-connector Fig. 3, and it may be added here, in similar access to the code-connector Fig. 4, as will appear presently. With this in mind, we will now assume that one of these 80 connectors, not shown, has gained seizure of the code connector Fig. 3, in the manner described, with relation to the connector A, controlled by a calling party. Further, that the responding party has gained telephonic 85 connection with the calling party through a second connector as A2, not shown, in the manner set forth hereinbefore with relation to telephone T2 and connector A2.

Under the above assumed condition connectors A and A2 and telephones T and T2 are in normal condition. Code-connector 90 Fig. 3 and the two connectors not shown are in co-operation and the calling and the called parties are in telephonic communication. Under this condition there will be 95 ground potential on bank contact 48 and multiples thereof, and bank contact 207 and multiples thereof. It will be clear presently that a ground now (and does normally) exists on bank contact 220, conductor 221, and bank contact 94 and multiples thereof.

It will now be assumed that party at telephone T desires to gain communication with the party having the code-call to two bells. 100 He will initiate the call as before set forth, and call telephone number "39" as in the before exemplified instance. However, since bank contact 48 now constitutes ground potential, and as will appear presently, bank 105 contact 64 constitutes battery potential, the connector A will, upon its wiper 45 engaging bank-contact 48 be caused to automatically rotate its wipers so that wiper 45 will engage bank contact 64 and seize in a manner as hereinbefore fully set forth. The described circuit-path traced from the calling telephone T to the wipers 18 and 19 will now be completed from wiper 18 to bank contact 95, conductor 96, contact 401, conductor 402, conductor 403 to the upper-winding of relay 110 404 and from the lower winding of the latter relay through contacts 405, spring 406, armature 407, conductor 408, bank contact 97 to wiper 19; relay 404 actuating, applying ground on its armature 409 to the winding of slow-releasing relay 410, causing it to actuate. The calling party will now transmit digit "1" in the manner as before described, 115 whereupon relay 404 will deactuate and re-

actuate one time, transmitting a ground impulse from armature 409, contact 411, armature 412, winding of slow releasing relay 413, winding of vertical magnet V4, side-switch 5 wiper 414 to battery, causing the vertical magnet V4 to actuate one time and step the shaft carrying wipers 415 to 419 one vertical step and register in line with the first set of bank contacts. The current derived 10 through relay 413 will cause it to attract its grounded armature 420 into engagement with its operating contact and apply ground to the winding of the private magnet P4, causing it to actuate, preparatory to releasing the side-switch wipers 414 and 421, upon 15 its deactuation, permitting them to move into their second positions respectively. This occurs upon the deactuation of relay 413, its period after the deenergization of the vertical magnet V4 following the current impulse.

The calling party will now transmit digit "2" in the manner as before described, whereupon relay 404 will deactuate and reactuate two times, transmitting a series of two impulses over the described circuit, including the winding of relay 413, winding of the rotary-magnet R4 to side-switch wiper 414 (now in second position) to battery. Relay 30 413 will actuate as before, and due to its slow-release characteristic will sustain until its period has expired following the last impulse of the series. The same functioning of the private magnet P4 ensues as before 35 upon the retraction of armature 420, permitting the side-switch wipers 414 and 421 to move into their third positions respectively. Resultant to the described energization of, and the operation of the rotary magnet R4 40 the wipers 415 to 419 are caused to be driven two rotary steps engaging bank contacts 422 to 426 inclusive. However, bank contacts 424 and 425 have no operative purpose being disassociated from the circuits.

45 Upon the side-switch wipers 414 and 421 advancing into their third positions respectively, a circuit path may be traced from ground on contact 427, side-switch wiper 421, winding of relay 428, side-switch 414 to battery; relay 428 actuating. A circuit path 50 can now be traced from the winding of relay 429, armature 430, to grounded armature 431; relay 429 actuating, and applying wipers 415 to 418 to conductor 344. Also a 55 circuit may be traced from conductor 344, wiper 416, bank contact 423, conductor 432, conductor 349, to contact 504, and from conductor 344, wiper 415, bank contact 422, conductor 433, conductor 350 to contact 505. 60 Ground on armature 434 will be applied to conductor 435, conductor 347 to the winding 65 of relay 541, causing it to actuate. A circuit path may now be traced from grounded armature 431, armature 436, wiper 419, bank contact 426, conductor 437, to lamp 538, caus-

ing it to glow, and therefore, indicating to the attendant that the code transmitting equipment is under operative control of the code-connector Fig. 4 and that it is transmitting series of two bells as indicated by the specific lamp. However, it will be noted presently that upon the response of the called party that armature 431 attracts and removes the ground applied to the wiper 419 and to the lamp 538, whereupon it will extinguish. That is, the lamp 538 will be caused to glow from the time the code-sending equipment is seized until a response is obtained from the called party or the code-connector Fig. 3 is caused to restore.

At the time bank contact 64 was engaged by wiper 45 the said bank contact constituted battery potential, having received it through resistance 440 and conductor 441. However, incident to the seizure of the said bank contact connector A causes its wiper 45 to change the said battery potential to ground potential as hereinbefore set forth. Also, ground potential existed on bank contacts 220 and 94, received from grounded 90 armature 442, armature 443, armature 444, conductor 445 and conductor 221. This ground potential applied over conductor 445 is changed to battery potential incident to actuation of relay 404 described. The conductor 445 traced to armature 443 is now applied through resistance 446 to battery. Thus, the leading-in conductors (441, 96, and 408) to Fig. 4 cannot now be seized by a second connector. The leading-out terminals are seizable having been unguarded by the change from ground potential on conductor 445, similarly to the functioning of Fig. 3 described. At the time conductor 441 became grounded this ground is communicated to armature 447, conductor 448 to conductor 353 and over the before described path to the winding of relay 559 causing it to actuate to disassociate the plates 507 to 512, thus guarding the code transmitting equipment against intrusion by the attendant through the agency of plug 513.

From the foregoing it will be manifest that until relay 377 (in Fig. 3) actuated, after the seizure of the code-connector, a busy ground is applied to the leading-in test conductor of code-connector Fig. 4 by way of contact 352, conductor 353, conductor 448, armature 447, conductor 441, conductor 221 to bank contacts 64 and 225 and multiples. This is to insure that but one code-connector can be in a seized condition if not responded to by the called party; that is to say, but one code-connector can't have its wipers in circuit continuity with conductor 344. Thus, when a connector has seized a code-connector and the code transmitting equipment is operatively functioning due to a code-connector having initiated a code-call the other code-connector is rendered busy 120 125 130

against seizure by a connector. It will appear presently that if the code-transmitting equipment is operatively functioning due to a code-call having been initiated by the attendant through the agency of plug 513, both code-connectors Figs. 3 and 4, are rendered busy against seizure by a connector; this condition enduring until the plug 513 is disassociated from the plates 507 to 512.

10 Recapitulating, we now have lamp 538 glowing, relay 541 actuated, and contacts 504 and 505 attached to conductor 344. It will be remembered that the actuation of relay 541 initiated the rotation of the motor

15 M (relay 576 being normal). As arm 501 engages contact 502 and 503 there will be no operative effect resultant thereto, as these contacts are unattached. However, upon the arm progressing and engaging contact 504,

20 a circuit may be traced from the plus pole of the supply source Ge, through the winding of relay 546, arm 501, contact 504, conductor 349, conductor 432, bank contact 423, wiper 416, conductor 344, armature 543 to

25 conductor 542 leading to the minus pole of the supply source Ge; relay 546 actuating and causing the gongs 516 and 517 to sound as set forth hereinbefore. Upon the wiper 501 progressing to and engaging contact 505

30 the circuit traced from the plus pole of the supply source to wiper 501 will be continued to contact 505, conductor 350, conductor 433, bank contact 422, wiper 415, conductor 344, armature 543, to conductor 542

35 leading to the minus pole of the supply source Ge. Relay 546 will thus actuate and cause the gongs 516 and 517 to sound as before. Upon the wiper 501 advancing and engaging contact 506 the functioning of drive magnet D5 will ensue as before set forth to advance wiper 521.

Assume now that the called party removes the receiver from the switch-hook of a convenient telephone and initiates the call, as described hereinbefore with relation to the responding party, and dials telephone number "28" as before, causing connector A2 to step up and rotate its wipers to the bank contact set corresponding to bank position

50 "28." Bearing in mind that bank contact 207 engaged by wiper 60 constitutes ground potential due to the assumed telephonic service established through code-connector Fig. 3, the connector A2 will cause its said wiper

55 60 (and companion wipers) to rotate off the said bank contact 207 and into engagement with bank contact 220, which, as has been set forth, constitutes battery potential under the stated condition and is therefore seizable.

60 A circuit can now be traced from telephone T2 over the described circuit path to wipers 205 and 206 and to engaged bank contacts 222 and 223 respectively. The circuit path will thence follow from bank contact 222, conductor 224, conductor 98, armature

449, armature 450 to grounded signaling current source G4 and from the inside-winding of relay 451 armature 454, contact 455, conductor 456, conductor 101 to bank contact 223, causing relay 451 to actuate. The circuit traced including the responding telephone T2 will thus be continued from armature 450 to conductor 465 and to the lower winding of relay 466, and from the upper winding of relay 466 to conductor 467 and to armature 454; relay 466 actuating. A locking circuit for relay 451 will be established through its armature 468, off-normal spring 461 to grounded spring 462.

Bearing in mind that the calling party is assumed to be holding the receiver off the switch-hook at telephone T and that therefore relays 404, 410, 428, and 429 are actuated, a circuit can now be traced from leading-in conductor 96, contact 401, conductor 402, armature 457, inside winding of relay 458 to battery and from leading-in conductor 408, armature 407, armature 459 to the grounded signal current source G4'. Relay 458 is designed to be inoperative to current projected from the signal current source G4' under the condition, for example, of the receiver at calling telephone T being on the switch-hook but that it will be operative to the current traversing the stated conductive path, including the receiver (off the switch-hook) at telephone T, therefore, relay 458 will actuate. A locking circuit for relay 458 is established from the outside winding of the said latter relay, contact 460, off-normal spring 461, to grounded spring 462. The telephonic circuit traced from the calling telephone T to leading-in conductors 96 and 408 will now be joined through contacts 463 and 464 to conductors 467 and 465 respectively, which latter have been described as including the responding telephone T2, so that the calling and responding telephones are in telephonic connection. Under the assumed condition code-connectors Fig. 3 and

Fig. 4 are linked in two independent established telephonic connections, and in view of the hereinbefore descriptions are guarded against seizure through their leading-in conductors by virtue of bank-contacts 48 and 64, 115 and 59 and 225 respectively, and multiples thereof, constituting ground potential, and that they are further guarded against seizure through their leading-out conductors by virtue of bank contacts 102 and 94, and 207 and 220 respectively, and multiples thereof, constituting ground potential.

At the time relay 451 actuates and its armature 431 attracts, relay 429 will deactivate. Also upon armature 447 attracting, the described ground applied from conductor 441 through said armature, conductor 448, conductor 353, contact 558 to the winding of relay 559 will be opened, and relay 559 will deactivate, thus enabling the attendant

to gain control of the code transmitting device through the agency of plug 513 as set forth. Of course, the attendant will know that the code transmitting device is available to her by reason of the fact that lamp 533 extinguished consequent to relay 343 deactuating and that lamp 538 extinguished consequent to relay 429 deactuating.

Still assume that two telephonic connections are in establishment, with the code-connectors Figs. 3 and 4 as links therein respectively, and that the attendant now initiates the code-calling to cause the gongs to effectuate series of two strokes, intending to summon the party having that code-call. We will assume for now that in lieu of the calling party at telephone T having the service established through connector A a service has been established from some other telephone, not shown through a similar connector not shown, and also that the responding party having a service established through connector A2 has established it through a similar connector not shown. Thus, connectors A and A2 are assumed disengaged at the present, but that Figs. 3 and 4 are in the operative condition as last described.

Upon the party having the code-call of two bells hearing the signals, and responding from a convenient telephone, as the responding parties have done in the descriptions heretofore herein, by removing the receiver from the switch-hook and calling telephone number "28," the connector A will thereupon step-up and rotate into bank contact set "28."

In view of bank contacts 102 and 94 (and multiples thereof) constituting ground potential they will not be seizable to the wiper 45 and therefore, it (and its companion wipers) will be caused to rotate off both of these contacts into engagement with bank contact 103, which being free, constitutes battery potential through the resistance 227, and the connector A will therefore seize in the manner as before set forth.

It will be manifest, presently that a telephonic circuit will now exist from the responding telephone T to the attendant's telephone T' and that the signal bell 105 thereat will vibrate, signaling the attendant, who upon responding, is in telephonic connection with the responding called party at telephone T.

When wiper 45 of connector A engaged bank contact 103 (corresponding to telephone number "20") off-normal sets 3 and 4 will be in normal condition, as set forth at the outset. Therefore, relays K and D will be normal so the operative circuit path from telephone T will be continued from spring 21, conductor 20 to the upper winding of relay N and from contact 28, conductor 29 to lower winding of relay N, thus

sustaining relay B, though ground potential is maintained on conductor 33 from grounded spring of off-normal set 5 through armature 106 of relay D. Relay H having actuated in the manner before set forth signaling current from grounded source G' will be applied through armature 107 of relay F, armature 77, conductor 78, contact 79, wiper 19, bank contact 104, conductor 108, condenser 109, bell ringer 105, conductor 110, bank contact 111, wiper 18, armature 112 of relay K, armature 75, conductor 76, armature 113, of relay K, armature 114 of relay F to the inside winding of relay F. The ringer 105 will vibrate, energized over the traced path from source G, and the attendant will respond by removing the receiver from the switch-hook of telephone T'. A conductive circuit through the receiver at telephone T' including the inside winding of relay F and the latter described path will now be closed and relay F will actuate, it not having been susceptible to the signaling circuit described as traversing its inside winding over the inductive path including the condenser 109. Upon actuating, relay F will lock its outside winding to armature 115 to the lower grounded spring of off-normal set ON. The upper terminal of the lower winding of retardation coil E will become grounded at armature 115. Relay F being now actuated, battery and ground through the windings of the retardation coil E will be applied over the traced conductors including the receiver and transmitter of telephone T'. Noting that the described paths traced to telephones T and T' respectively are inductively united by condensers 116 and 117, it will appear the responding party called and the attendant are in telephonic communication. Of course, the attendant could have established connection by inserting a plug of a well known form of cord circuit into springjack 118 and gained telephonic communication with telephone T equivalently to removing the receiver from the switch-hook, as described.

The release of the connector A under this condition is dependent upon the party at telephone T, who upon replacing the receiver on the switch-hook causes relay N to be deenergized, whereupon it will deactuate followed by relay B its period thereafter. Bearing in mind that relay J is normal, a circuit can now be traced from the lowermost armature of relay H, winding of release magnet Re, spring 84, armature 85, armature 34, to grounded armature 32, causing the release magnet Re to actuate, and restore the connector A as before described.

Referring now to Fig. 5 it will be observed that when the operator caused the code series of two bells to be transmitted, plug 513 was inserted to engage the plates 507, 508, 511 and 512 along the line 535 and 536.

that therefore a circuit was established from conductor 542, armature 569, conductor 570, plate 507, plug 513, plate 508, conductor 571, armature 572, winding of relay 573 to the 5 minus terminal of the motor M, causing the said motor to be energized and start its rotation, the lower set of contacts of off-normal set ON5 forming a by-pass for the above described circuit upon the arm 501 10 moving off-normal. The conductors leading from plates 509 and 510 have no operative effect at the present, since they have no conductive connection to the plug 513 and to the other plates 507, 508, 511 and 512. It 15 will be noted that contact 505 leads by way of armature 574 to plate 512 and that contact 504 leads by way of armature 575 to plate 511, the latter plates it will be remembered are in electrical connection to the plug 20 513 and with both plates 507 and 508, and therefore, in view of the lower set of contacts of off-normal set ON5 being closed, lead to the minus pole of the supply source Ge. It has been set forth that a circuit 25 path from arm 501 leads through relay 546 to the positive pole of the supply source Ge, therefore when wiper 501 engages contact 504, a circuit will be completed from contact 504, armature 575, plate 511, plug 513, 30 plate 507, armature 569, to the minus pole of the supply source Ge, causing relay 546 to actuate in the manner as before set forth to cause one stroke of the gongs 516 and 517, and when the arm 501 engages contact 505 it 35 completes a circuit by way of armature 574, plate 512, plug 513 plate 507, armature 569 to the minus pole of the supply source Ge, again causing the relay 546 to actuate and cause one stroke of the gongs 516 and 517. 40 The arm 501 will continue to rotate until the plug 513 is removed, and will then rotate, because of the off-normal springs, ON5 until it returns to its normal angular position in the manner as hereinbefore set forth. 45 Conductor 347 being ungrounded and therefore relay 541 is normal, the circuit leading over conductor 533 from contact 506 now passes directly from armature 552 to its resting contact 556, conductor 557 direct to 50 the negative pole of the supply source Ge, and not by way of conductor 551 and the winding of drive magnet D5 of switch S. Therefore, the switch S will remain inert 55 when the code transmitting equipment is under control of the attendant through the agency of the plug 513. Relay 573 which closes upon the call being initiated by the attendant through the agency of plug 513, applies ground from contact 575 to the 60 winding of slow releasing relay 576, causing it to actuate and lock from its armature 577 to the grounded topmost spring of off-normal set ON5. This will apply ground from contact 578 to conductor 353. It will, 65 therefore, be noted that if conductors 301 or

441 are not grounded by reason of Fig. 3 or Fig. 4 being respectively seized by a connector, the said conductors 301 and 441 will receive ground to guard the respective code-connectors against seizure by a connector. 70 Thus while the code-call is transpiring, initiated by the attendant through the agency of plug 513 code connectors Figs. 3 and 4 are guarded against seizure, and will, therefore, prevent confusion. Should the attendant 75 remove the plug 513 as provided, while the arm is in off-normal position and its dependent off-normal contact sets ON5 are operated relay 576 will remain locked until after its period after arm 501 returns to normal, 80 and during the said actuated condition of relay 576, conductor 353 is maintained grounded for the object set forth. Also if either code-connector Fig. 3 or Fig. 4 should be released and its leading-in conductors become inherently unguarded and seizable, due to contact 579 being engaged by armature 577 (relay 576 not having been actuated under the condition of the code transmitting 85 device having been in control of a code-connector) an off-normal condition of arm 501 will insure ground being maintained on conductor 353, and to the winding of relay 559 causing it to become actuated from the topmost spring of off-normal set ON5 for 90 the object set forth, and to incapacitate the code transmitting device against the attendant and code connectors until the said arm 501 returns to normal. 95

The general operation of Fig. 4 will be obvious in view of the specific description thereof, and in view of the detailed description of code-connector Fig. 3, and it is therefore thought that those skilled in the art will be able to clearly understand the operation 100 and function of code connector Fig. 4, it being almost identical with that of code-connector Fig. 3. 105

It will be noted that signaling current source G3' and G4' is differently interrupted than that generally used throughout the figures. This is to enable the party receiving a call being able to identify its source. 110

It will be perceived from the foregoing 115 description that a responding party will always call the same telephone number, "28" in the exemplified instance, and that due to the busy conditions set up will always be directed to the telephone or station having 120 called him; this also being true wherein the code-call emanates from the attendant's station through the agency of plug 513. In the latter case a busy condition is set up or maintained in both code-connectors Fig. 3 and Fig. 4 regardless of their busy or idle state, whereby the responding party will be automatically directed to the attendant's telephone, resultant to his calling the usual 125 telephone number, as "28". The party at a 130

telephone initiating a code-call will always dial the same primary number, as "39" in the exemplified form of the invention chosen for its elucidation.

It is manifest that but one code-connector may be employed or that more than the two shown may be employed, depending upon traffic conditions in any installation.

The connectors A and A2 (which are 19) selectors when cooperating with Figs. 3 and 4) being so designed as to require battery potential to be encountered by the test wipers 45 and 60 respectively to cause a seizure, the code-connectors Figs. 3 and 4 15 and other co-operating elements are designed to meet the requirements of the said connectors; resistances 227, 302, 384, 440 and 446 being examples. It is manifest that should any of the well known forms of 20 selectors, or connectors having the function of seizing either upon the test wiper encountering battery potential or no potential, the cooperating circuits and the code-connectors Figs. 3 and 4 may be readily modified by removing the said resistance, and changing other relevant details.

In the description and drawings connectors A and A2 are shown accessible to local telephones of the private automatic exchange. It is to be understood that the 30 invention is capable of being applied to connectors (which, of course, operate as selectors as do the said A and A2) terminating trunk lines in the private automatic exchange in lieu of local lines, or as supplementary thereto. That is to say, that the code-connectors in Figs. 3 and 4 are commonly accessible to local connectors and trunk connectors, the latter enabling parties calling over the trunks from the main exchange to cause code-calling as set forth from the local telephones, as T and T2.

It is, of course, manifest that an example of larger nominal capacity than exemplified may be organized employing the present invention, by introducing intermediate switches involving one or more additional numerical orders and, therefore, requiring a corresponding change in the predetermined calling and responding numbers used in code-calling. It is also manifest that other various, more or less detailed modifications, by way of amplification, curtailment or alteration of the exemplified circuits and equipments may be made by those skilled in the art to which the present invention belongs without departing from its scope, in view of the subjoined claims.

Having thus described one exemplified form of the invention, what I claim as new and desire to secure by United States Letters Patent is:

1. In a telephone system a calling telephone leading over a calling line to a selector, a called line, a cooperative successive

switch, means on the calling line to direct the operation of the selector to effect its connection with the successive switch, and for directing the operation of the successive switch into selective relation with the called line and for applying a signaling current thereon, and means whereby the telephone on the calling line may be restored to normal idle position before a response is obtained on the called line without restoring the selector and its successive switch. 70

2. In a telephone system a calling telephone leading over a calling line to a selector, a called line, a cooperative successive switch, means on the calling line to direct the 80 operation of the selector to effect its connection with the successive switch, and for directing the operation of the successive switch into selective relation with the called line and for applying a signaling current thereon, means whereby the receiver of the telephone on the calling line may be restored to normal idle position without restoring the selector and its successive switch, and means whereby if the receiver of the calling 85 telephone is thereafter removed the said selector and successive switch will restore. 90

3. In a telephone system a calling telephone leading over a calling line to a selector, a called line, a cooperative successive switch, means on the calling line to direct the 95 operation of the selector to effect its connection with the successive switch, and for directing the operation of the successive switch into selective relation with the called line, and means whereby the telephone on the calling line may be restored to normal idle position before a response is obtained on the called line without restoring the selector and its successive switch. 100

4. In a telephone system a calling telephone leading over a calling line to a pre-selector accessible to a selector, a cooperative successive switch accessible to the selector, means on the calling line to cause the pre-selector to automatically select the selector, control means on the calling line to direct the operation of the selector in selecting and connecting with the successive switch and for directing the operation of the successive switch into selective relation with a called line and for applying signaling current thereon, means whereby the receiver of the telephone on the calling line may be restored to normal idle position without restoring the selector and its cooperative successive switch, and means whereby if the receiver of the calling telephone is thereafter removed the said selector and successive switch will restore. 115

5. In a telephone system a calling telephone leading over a calling line to a pre-selector accessible to a selector, a cooperative successive switch accessible to the selector, means on the calling line to cause the 120

pre-selector to automatically select the selector, control means on the calling line to direct the operation of the selector in selecting and connecting with the successive switch and for directing the operation of the successive switch into selective relation with a called line and for applying signaling current thereon, means whereby the receiver of the telephone on the calling line 5 may be restored to normal idle position without restoring the selector and its cooperative successive switch, and means whereby if the receiver of the calling telephone is thereafter removed the said selector and successive 10 switch will restore and the pre-selector will reoperate to select the selector.

6. In a telephone system a calling telephone leading over a calling line to a pre-selector accessible to a plurality of selectors, a plurality of cooperative successive switches accessible to the selectors, means on the calling line to cause the pre-selector to seize the selector, control means on the calling line to direct the operation of the selector in selecting and connecting with one of the said successive switches and for directing the operation of the selected successive switch into selective relation with a called line and for applying signaling current thereon, means 20 whereby the receiver of the telephone on the calling line may be restored to normal idle position without restoring the selector and its cooperative successive switch, and means whereby if the receiver of the calling telephone is thereafter removed the said selector and successive switch will restore.

7. In a telephone system a calling telephone leading over a calling line to a pre-selector accessible to a plurality of selectors, a plurality of cooperative successive switches accessible to the selectors, means on the calling line to cause the pre-selector to seize the selector, control means on the calling line to direct the operation of the selector in selecting and connecting with one of the said successive switches and for directing the operation of the selector successive switch into selective relation with a called line and for applying signaling current thereon, means 40 whereby the receiver of the telephone on the calling line may be restored to normal idle position without restoring the selector and its cooperative successive switch, and means whereby if the receiver of the calling telephone is thereafter removed the said selector and successive switch will restore and the pre-selector will reoperate to select a disengaged selector.

8. In a telephone system a calling telephone line leading to an automatic switch, a successive switch accessible from the automatic switch, means controlled over the calling line to cause the automatic switch to connect with the successive switch, means in 50 the successive switch for causing the calling

line and a called line to be connected therethrough, means in the successive switch for applying signaling current to operate a signal device on the called line, means whereby the receiver of the calling telephone may be restored without restoring the said switches, and means whereby removing the receiver will restore the said switches.

9. In a telephone system a calling telephone line leading to an automatic switch, a successive switch accessible from the automatic switch, means controlled over the calling line to cause the automatic switch to connect with the successive switch, means in the successive switch for causing the calling line 75 and a called line to be connected therethrough, means for applying signaling current to operate a signal device on the called line, means whereby the receiver of the calling telephone may be restored without restoring the said switches, and means whereby removing the receiver will restore the said switches.

10. In a telephone system a calling telephone line leading to an automatic switch, a successive switch accessible from the automatic switch, means controlled over the calling line to cause the automatic switch to connect the successive switch, means in the successive switch for applying signaling current 90 to operate a signal device on the called line, means whereby the receiver of the calling telephone may be restored without restoring the said switches, and means whereby upon the response on the called line signaling current will be projected over the calling line from the successive switch to operate a signal device thereon.

11. In a telephone system a calling telephone line leading to an automatic switch, a successive switch accessible from the automatic switch, means controlled over the calling line to cause the automatic switch to connect with the successive switch, means for applying signaling current to operate a signal device on the called line, means whereby the receiver of the calling telephone may be restored without restoring the said switches, and means whereby upon the response on the called line signaling current will be projected 105 over the calling line to operate a signal device thereon.

12. In a telephone system a calling telephone line leading to a first automatic switch having access to a second automatic switch, a code call transmitting device, means controlled over the calling line to operate the first and the second switches to control said code device, means whereby when the receiver of the calling telephone is restored the code device will continue to operate, and a control device which will restore the switches to normal after a predetermined operation of the code device if the receiver remains restored.

13. In a telephone system a calling tele-

- phone line leading to a first automatic switch having access to a second automatic switch, a code call transmitting device, means controlled over the calling line to operate the first and the second switches to control said code device, means whereby when the receiver of the calling telephone is restored the code device will continue to operate, and a control device which will restore the switches 10 to normal after a predetermined operation of the code device if the receiver of the calling telephone has been restored and is so retained.
14. In a system of the character described, 15 an automatic telephone system including telephone lines, automatic switches and a code call device whereby a calling party may operate said switches and code equipment over the telephone lines, in combination with 20 an attendant's station having manually operated independent switches for directly setting the code device.
15. In a system of the character described, 25 an automatic telephone system including telephone lines, automatic switches and code call equipment whereby a calling party may operate said switches and code equipment over the telephone lines, in combination with an attendant's station having manually operated independent switches for directly setting the code equipment, and means to prevent interference between operation of the code equipment from the attendant station or from a telephone line.
16. In a system of the character described, 30 an automatic telephone system including telephone lines, automatic switches and code call equipment whereby a calling party may operate said switches and code equipment over the telephone lines, in combination with an attendant's station having manually operated independent switches for directly setting the code equipment, and means to prevent interference between operation of the code equipment from the attendant station or from a telephone line.
17. In a system of the character described, 35 an automatic telephone system including telephone lines, automatic switches and code call equipment whereby a calling party may operate said switches and code equipment over the telephone lines, in combination with an attendant's station having manually operated independent switches for directly setting the code equipment, and means whereby the called party may automatically connect with the calling party whether the call originates over a telephone line or from the attendant's cabinet by calling automatically a sole predetermined number.
18. In a system of the character described, 40 an automatic telephone system including telephone lines, automatic switches and code call equipment whereby a calling party may operate said switches and code equipment over the telephone lines, in combination with an attendant's station having manually operated independent switches for directly setting the code equipment, and means whereby the called party may automatically connect with the calling party whether the call originates over a telephone line or from the attendant's cabinet by calling automatically a sole predetermined number.
19. In a system of the character described, 45 an automatic telephone system including telephone lines, automatic switches and a code call device whereby a calling party may operate said switches and code equipment over the telephone lines, in combination with an attendant's station having manually operated independent switches for directly setting the code device, and means to prevent access to said code device while operating from a telephone line or through the manual switches of the attendant's station until the code device restores to normal.
20. In a system of the character described, 50 an automatic telephone system including telephone lines, automatic switches and code call equipment whereby a calling party may operate said switches and code equipment over the telephone lines, in combination with an attendant's station having manually operated switches for directly setting the code equipment, means whereby the called party may automatically connect with the calling party whether the call originates over a telephone line or from the attendant's cabinet by calling automatically a sole predetermined number, and visual signals at the attendant's station to indicate the code being transmitted and the party being called by the code call.
21. In a system of the character described, 55 an automatic telephone system including telephone lines, automatic switches and a code call device whereby a calling party may operate said switches and code equipment over the telephone lines, in combination with an attendant's station having manually operated independent switches for directly setting the code device with means to prevent seizure of a switch for code calling from an automatic telephone line and incapacitate the code device against setting from the attendant's station during the transmission of a code call.
22. In a system of the character described, 60 an automatic telephone system including telephone lines, automatic switches and a code call device whereby a calling party may operate said switches and code device to
- telephone lines, automatic switches and code call equipment whereby a calling party may operate said switches and code equipment over the telephone lines, in combination with an attendant's station having manually operated independent switches for directly setting the code equipment, a telephone at the attendant's station, means whereby the called party may signal automatically the telephone whether the call originates over one of the telephone lines or at the attendant's station by calling automatically a sole predetermined number.
23. In a system of the character described, 65 an automatic telephone system including

transmit a code call indexing a certain party, means whereby the called party may connect with the calling line by calling a sole predetermined number common to all 5 codes called, and means whereby the code device may be operated to transmit another code call while the first code called connection is still up.

23. In a system of the character described, 10 the combination with an automatic telephone system including telephone lines, automatic switches and a code call device whereby a calling party may operate said switches and code device to transmit a code call indexing a predetermined number and whereby the 15 called party may connect with the calling line by calling automatically a sole predetermined number common to all codes called, of means whereby a plurality of such 20 code called connections may exist at the same time.

24. In a system of the character described, 25 an automatic telephone system including telephone lines, automatic switches and a code call device whereby a calling party may from his telephone operate said switches and code device to transmit a code indexing a definite party, means whereby said code 30 device will operate indefinitely so long as the calling telephone is in its operated condition, means whereby said code device will continue its said operation for a predetermined period after the calling telephone is restored to normal, and means whereby the 35 calling party can terminate the code call at any time by again operating his telephone after it was restored.

25. In a system of the character described, 40 an automatic telephone system including telephone lines, automatic switches and a code call device whereby a calling party may from his telephone operate said switches and code device to transmit a code indexing a definite party, means whereby said code 45 device will operate indefinitely so long as the calling telephone is in its operated condition, means whereby said code device will continue its said operation for a predetermined period after the calling telephone is 50 restored to normal, means whereby the calling party can terminate the code call at any time by again operating his telephone after it was restored, and means whereby such 55 subsequent operation of the telephone will restore the operated switches provided no response has been secured from the called party.

26. In a system of the character described, 60 an automatic telephone system including telephone lines and automatic switches, a code call device, means whereby a calling party may from his telephone operate said switches and code device to call a predetermined code indexing a desired party, means 65 whereby the code device will continue to

send out code calls after the calling party restores his telephone, and means whereby the party in responding to the code call can connect with the calling telephone by calling automatically a predetermined number. 70

27. In a system of the character described, 75 an automatic telephone system including telephone lines and automatic switches, a code call device, means whereby a calling party on one of said lines may from his telephone operate said switches and code device to call a predetermined code indexing a desired party, means whereby the code device will continue to send out code calls after the calling party restores his telephone, and 80 means whereby the party in responding to the code call can automatically connect with and signal the calling line although restored, by calling automatically a sole predetermined number regardless of which one of 85 said lines is said one line.

28. In a system of the character described, 90 an automatic telephone system including telephone lines, automatic switches and a code call device whereby a calling party on one of said lines may from his telephone operate said switches and code device to transmit a code call indexing the number of a desired party, means for preventing the operated apparatus from restoring although 95 the calling party restores his telephone, and means whereby the party responding to the code call may connect with the calling line although restored through unrestored apparatus by calling automatically a sole predetermined number regardless of which one of 100 said lines is said one line.

29. In a system of the character described, 105 an automatic telephone system including telephone lines, automatic switches and a code call device whereby a calling party on one of said lines may from his telephone operate said switches and code device to transmit a code call indexing the number of a desired party, means for preventing the operated apparatus from restoring although 110 the calling party restores his telephone, and means whereby the party responding to the code call may connect with and signal the calling line although restored through unrestored apparatus by calling automatically a sole predetermined number regardless of which one of 115 said lines is said one line.

30. In a system of the character described, 120 an automatic telephone system including telephone lines and automatic switches, a code call device, means whereby a calling party on one of said lines may from his telephone operate said switches and code device to call a predetermined code indexing a desired party, means whereby the code device will continue to send out code calls after the calling party restores his telephone, means whereby the party in responding to the code call can automatically connect with and sig- 125

nal the calling line although the telephone thereon is restored, by calling automatically a predetermined number non-specific to said one line, and means whereby the called party will get the signaling tracing indicating that a line is being signaled.

31. In a system of the character described, an automatic telephone system including telephone lines and automatic switches, a ¹⁰ code call device, means whereby a calling party on one of said lines may from his telephone operate said switches and code device to call a predetermined code indexing a desired party, means whereby the code device will continue to send out code calls after the calling party restores his telephone, means whereby the party responding to the code call can automatically connect with and signal the calling line although the telephone ²⁰ thereon is restored, by calling automatically a predetermined number non-specific to said one line, and means whereby the called party can restore the switches if the calling party does not respond.

25 32. In a system of the character described, an automatic telephone system including telephone lines, automatic switches and a code device whereby a calling party on one of said lines may from his telephone operate ³⁰ said switches and code device to send a code indexing the number of a predetermined party, means whereby the called party may connect with the calling line by calling automatically a predetermined number non-specific to said one line, means whereby the code device will operate for a predetermined period after the calling telephone is restored following the code call, and means whereby the apparatus used in setting up the code ³⁵ ⁴⁰ call is restored upon cessation of the code call.

33. In a system of the character described, an automatic telephone system including telephone lines, automatic switches and a ⁴⁵ code call device whereby a calling party on one of said lines may from his telephone operate said switches and code device to transmit a code call indexing a certain party and means for audibly indicating on the ⁵⁰ said one of said lines when the code call is indexing said certain party.

34. In a telephone system of the character described, an automatic telephone system including telephone lines, automatic switches ⁵⁵ and a code call device whereby a calling party may operate said switches and code device to transmit a code call indexing a certain desired party, means whereby the called party may connect with the calling line by calling a predetermined number, means whereby a plurality of such code called connections may exist at the same time, the last said means including a plurality of normally unselectable contacts extending to certain ones of said automatic switches and calling ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ line terminals, and means for rendering the terminal of the calling line and operated switch selectable to the call back from the called line.

35. In a telephone system, a calling line, an automatic switch, a called line, a calling signaling device on the calling line and also on the called line, signaling current, a manually operated circuit-closing switch on the calling line, means operative only while the last said switch is operated for extending a call from the calling line through the switch to the called line, means for thereafter applying signaling current to the called line, and means for applying signaling current effective to the signaling device on the calling line consequent to a response on the called line only if the said circuit-closing switch has been restored antecedent to the response.

36. In a telephone system, a calling line, an automatic switch, a called line, a calling signaling device on the calling line and also on the called line, signaling current to which a condenser is transparent, a manually operated circuit-closing switch on the calling line, means operative only while the last said switch is operated for extending a call from the calling line through the switch to the called line, means for thereafter applying signaling current to the called line, and means for applying signaling current effective to the signaling device on the calling line consequent to a response on the called line only if the said circuit-closing switch has been restored antecedent to the response.

37. In a telephone system, a calling line, an automatic switch, a called line, a calling device on the calling line, a calling signaling device on the calling line and also on the called line, signaling current to which a condenser is transparent, a manually operated circuit-closing switch on the calling line, means operative only while the last said switch is operated for extending a call from the calling line to the called line under control of the calling device, means for thereafter applying signaling current to the called line, and means for applying signaling current effective to the signaling device on the calling line consequent to a response on the called line only if the said circuit-closing switch has been restored antecedent to the response.

38. In a telephone system, a calling line, an automatic switch, a called line, a calling device on the calling line, a calling signaling device on the calling line and also on the called line, signaling current, a manually operated circuit-closing switch on the calling line, means operative only while the last said switch is operated for extending a call from the calling line to the called line under control of the calling device, means for thereafter applying signaling current to the

called line, and means for applying signaling current effective to the signaling device on the calling line consequent to a response on the called line only if the said circuit-closing switch has been restored antecedent to the response.

39. In a telephone system, a calling line, an automatic switch, a called line, a calling signaling device on the calling line and also on the called line, first and second signaling current sources, a manually operated circuit-closing switch on the calling line, means operative only while the last said switch is operated for extending a call from the calling line through the switch to the called line, means for thereafter applying the said first source to the called line effective to the signaling device thereon, and means for applying the said second source to the calling line effective to the signaling device thereon consequent to a response on the called line only if the said circuit-closing switch has been restored antecedent to the response.

40. In a telephone system, a calling line, an automatic switch, a called line, a calling signaling device on the calling line and also on the called line, first and second signaling current sources in the switch, a manually operated circuit-closing switch on the calling line, means operative only while the last said switch is operated for extending a call from the calling line through the switch to the called line, means for thereafter applying the said first source to the called line effective to the signaling device thereon, and means for applying the said second source to the calling line effective to the signaling device thereon consequent to a response on the called line only if the said circuit-closing switch has been restored antecedent to the response.

41. In a telephone system, a calling line, an automatic switch, a called line, a calling signaling device on the calling line and also on the called line, first and second signaling current sources in the switch, the second said source being of a character to which a condenser is transparent, a manually operated circuit-closing switch on the calling line, means operative only while the last said switch is operated for extending a call from the calling line through the switch to the called line, means for thereafter applying said first source to the called line effective to the signaling device thereon, and means for applying the said second source to the calling line effective to the signaling device thereon consequent to a response on the called line only if the said circuit-closing switch has been restored antecedent to the response.

42. In a telephone system, a calling telephone line and a called line, an automatic switch, a calling signal device on the calling line and also on the called line, signaling

current sources, a receiver and switch-hook of the telephone on the calling line, a calling device on the calling line for operating the switch to complete a connection from the calling to the called line effective after removing the receiver from the switch-hook, means in the automatic switch for applying one of the said sources to the called line, means for restoring the automatic switch controlled by restoring the receiver on the switch-hook, means for delaying the restoration of the switch after the receiver is restored on the switch-hook until a predetermined time has elapsed, means for applying the other said source to operate the signal device on the calling line consequent to a response on the called line within the said predetermined time, and means whereby the switch will be forthwith restored by removing the receiver from the switch-hook after first restoring it.

43. In a telephone system, a calling telephone line and a called line, an automatic switch, a calling signal device on the calling line and also on the called line, signaling current sources, a receiver and switch-hook of the telephone on the calling line, a calling device on the calling line for operating the switch to complete a connection from the calling to the called line effective after removing the receiver from the switch-hook, means in the automatic switch for applying one of the said sources to the called line, means for restoring the automatic switch controlled by restoring the receiver on the switch-hook, means for delaying the restoration of the switch after the receiver is restored on the switch-hook until a predetermined time has elapsed, means for applying the other said source to operate the signal device on the calling line consequent to a response on the called line within the said predetermined time, and means whereby the switch will be forthwith restored by removing the receiver from the switch-hook after first restoring it if the restoration occurred after the called line has been connected with.

44. In a telephone system, a calling telephone line and a called line, an automatic switch, a calling signal device on the calling line and also on the called line, signaling current sources, a receiver and switch-hook of the telephone on the calling line, a calling device on the calling line for operating the switch to complete a connection from the calling to the called line effective after removing the receiver from the switch-hook, means in the automatic switch for applying one of the said sources to the called line, means for restoring the automatic switch controlled by restoring the receiver on the switch-hook, means for delaying the restoration of the switch after the receiver is re-

stored on the switch-hook until a predetermined time has elapsed, means for applying the other said source to operate the signal device on the calling line consequent to a response on the called line within the said predetermined time and for preventing the restoration of the switch at the said predetermined time.

45. In a telephone system, a calling telephone line, an automatic switch, a called line, a telephone receiver for inclusion in the calling line for energizing the switch preparatory to its operation upon removing the said receiver from its switch-hook, means controlled over the calling line for causing the said switch to connect the said calling line with the called line, means whereby the receiver may be restored to its switch-hook without destroying the connection, and means whereby thereafter removing the receiver from its switch-hook will destroy the connection.

46. In a telephone system, a calling telephone line, an automatic switch, a called line, means controlled over the calling line for causing the said switch to connect the said calling line with the called line, means for maintaining a closed path including the calling line, means whereby the closed path including the calling line may be opened without destroying the connection, and means whereby thereafter closing the said path will destroy the connection.

47. In a telephone system, a calling telephone line, an automatic switch, a called line, means controlled over the calling line for causing the said switch to connect the said calling line with the called line, means for maintaining a closed path including the calling line, means whereby the closed path including the calling line may be opened for a prolonged period without destroying the connection, and means whereby thereafter closing the said path will destroy the connection.

48. In a telephone system, a calling telephone line, an automatic switch, a called line, a signaling current source, a signaling indicator on the said calling line, a line relay in the switch, means controlled over the calling line for operating the line relay to cause the said switch to connect the said calling line to the called line, means to maintain the line relay restored to normal for a prolonged period without destroying the connection from the calling to the called line, and means to apply the signaling current to the calling line to operate the indicator if the line relay is restored to normal, consequent upon a response on the called line.

49. In a telephone system, a calling telephone line, an automatic switch, a called line, a telephone receiver for inclusion in the calling line for energizing the switch preparatory to its operation upon removing the

said receiver from its switch-hook, means controlled over the calling line for causing the said switch to connect the said calling line with the called line, means whereby the receiver may be restored to its switch-hook without destroying the connection, and means whereby thereafter closing a path between the talking conductors of the called line will prevent the operation of the switch to destroy the connection between the calling and called lines.

50. In a telephone system, calling and called telephone lines, an automatic switch, a signal device on the calling line, a source of signaling current, means to operate the switch to connect the calling line to the called line, means for preventing the restoration of the switch by maintaining a closed path between the talking conductors of the calling line, means to maintain the switch operated after terminating the closure of the said closed path, and means for applying the signaling current source to the calling line to operate the signaling device consequent to closing a path between the talking conductors of the called line.

51. In a telephone system, a calling telephone line, an automatic switch, a called line, a source of signaling current, a signaling device on the calling line, a telephone receiver for inclusion in the calling line for energizing the switch preparatory to its operation upon removing the said receiver from its switch-hook, means controlled over the calling line for causing the said switch to connect the said calling line with the called line, means whereby the receiver may be restored to its switch-hook without destroying the connection, and means whereby thereafter closing a path between the talking conductors of the called line will cause the signal current to be applied to operate the signaling device.

52. In a telephone system, a calling telephone line, an automatic switch, a called line, a source of signaling current, a signaling device on the calling line, a telephone receiver for inclusion in the calling line for energizing the switch preparatory to its operation upon removing the said receiver from its switch-hook, means controlled over the calling line for causing the said switch to connect the said calling line with the called line, means whereby the receiver may be restored to its switch-hook without destroying the connection, and means whereby thereafter closing a path between the talking conductors of the called line will cause the signaling current to be applied to operate the signaling device or alternatively closing a path between the talking conductors of the calling line will restore the switch.

53. In a telephone system, a calling telephone line, a called line, a link for connecting the calling and called lines, a source of

- signaling current, a signaling device on the calling line, means for maintaining a closed path including the talking conductors of the calling line, means whereby the closed path
- 5 including the said talking conductors of the calling line may be opened for a prolonged period without destroying the connection, and means whereby thereafter closing a path including the talking conductors of the
- 10 called line will cause the application of the signaling current to operate the signaling device.
54. In a telephone system, a calling telephone line, a called line, a link for connecting the calling and called lines, a source of signaling current, a signaling device on the calling line, means for maintaining a closed path including the talking conductors of the calling line, means whereby the closed path
- 15 including the said talking conductors of the calling line may be opened to automatically destroy the connection in a predetermined time thereafter, and means whereby thereafter closing a path including the talking
- 20 conductors of the called line within the said predetermined time will cause the application of the signaling current to operate the signaling device.
55. In a telephone system, a calling telephone line, a called line, a link for connecting the calling and called lines, a source of signaling current, a signaling device on the calling line, means for maintaining a closed path including the talking conductors of the
- 25 calling line, means whereby the closed path including the said talking conductors of the calling line may be opened to automatically destroy the connection in a predetermined time thereafter, means whereby thereafter closing a path including the talking
- 30 conductors of the called line within the said predetermined time will cause the application of the signaling current to operate the signaling device and also prevent the connection from being destroyed, and means for
- 35 thereafter destroying the connection consequent to opening the paths including the talking conductors of the calling and the called lines respectively.
56. In a telephone system, a relay, a signal circuit and signal device thereon operated by the relay, an impulse transmitting device for sending series of control impulses to correspondingly operate the relay, a calling line, a calling device on the calling line, a coordinate directional movement switch
- 40 controlled from the calling device, a set of wipers on the switch, a plurality of cooperative sets of bank contacts accessible to the wipers at various off-normal levels resultant to being driven coordinately, means for starting the operation of the said transmitting device upon the wipers being set upon a cooperative set of bank contacts, and means depending upon what set of bank
- 45 contacts the wipers of the switch have been set upon to determine what series of control impulses will be transmitted by the transmitting device.
57. In a telephone system, a relay, a signal circuit and signal device thereon operated by the relay, an impulse transmitting device for sending series of control impulses to correspondingly operate the relay, a calling line, a calling device on the calling line, a coordinate directional movement switch controlled from the calling device, a set of wipers on the switch, a plurality of cooperative sets of bank contacts accessible to the wipers at various off-normal levels resultant to being driven coordinately, and means depending upon what set of bank contacts the wipers of the switch have been set upon to determine what series of control impulses will be transmitted by the transmitting device.
58. In a telephone system, a relay, a signal circuit and signal device thereon operated by the relay, an impulse transmitting device for sending series of control impulses to correspondingly operate the relay, a calling line, a calling device on the calling line, a coordinate directional movement switch controlled from a calling device responsive to sending two series of control impulses, a set of wipers on the switch, a plurality of cooperative sets of bank contacts accessible to the wipers at various off-normal levels resultant to being driven coordinately, means dependent upon what set of bank contacts the wipers of the switch have been set upon to determine what set-up condition shall thereupon ensue in the transmitting device, and means dependent upon the said set-up condition to cause one of a plurality of predetermined specific impulse operations of the relay.
59. In a code call transmitting system, a device to emit a series of code soundings according to predetermined code, the series of soundings being repeated a plurality of times, and means to indicate to an auditor at the time the last sounding of a series occurs.
60. In a code call transmitting system, a device to display a series of code operations according to predetermined code, the series of operations being repeated a plurality of times, and means to indicate to an observer at the time the last operation of a series occurs.
61. In a telephone system, a calling line, an automatic switch, a called line, a calling signaling device on the calling line and also on the called line, signaling current of two characters, means for extending a call from the calling line through the switch to the called line, means for thereafter applying a first one of said signaling current sources effective to the signaling device on the called

line, means for applying the second one of said sources of signaling current effective to the signaling device on the calling line consequent to a response on the called line, and 5 means whereby the source of signaling current applied to a line signaled upon will affect the calling signaling thereon differently depending upon whether the call has been initiated from the line having the 10 signal device operated or from another line.

62. In a telephone system, a relay, a signal circuit and signal device thereon operated by the relay, an impulse transmitting device for sending series of control impulses to 15 correspondingly operate the relay, a calling line, a calling device on the calling line, a coordinate directional movement switch controlled from the calling device responsive to sending two series of control impulses, a set 20 of grounding wipers on the switch, a plurality of cooperative sets of bank contacts, accessible to the said wipers at various off-normal levels resultant to being driven coordinate, the individual bank contacts of 25 the respective sets being differently related to the transmitting device as regards the corresponding individual bank contacts of other said sets, means dependent upon what set of bank contacts the wipers of the switch have 30 been set upon to determine what set-up condition shall ensue in the transmitting device, and means dependent upon the said set-up condition to cause one of a plurality of predetermined specific impulse operations of the 35 relay.

63. In a telephone system, a calling line, a calling device on the calling line, a controlled line and signal device thereon, an impulse transmitting device for sending series of control impulses to correspondingly 40 affect the controlled line, a coordinate directional movement switch controlled from the calling device, a set of wipers on the switch, a plurality of cooperative sets of bank contacts accessible to the wipers, the individual bank contacts of the respective sets being differently related to the transmitting device as regards the corresponding individual bank contacts of other said sets, 45 means dependent upon what set of bank contacts the wipers of the switch have been set upon to determine what set-up condition shall thereupon ensue in the transmitting device, and means dependent upon the said set-up condition to cause one of a plurality of predetermined control operations to occur to the controlled line signal device.

64. In an automatic telephone system including telephone lines, automatic switches 50 and code call mechanism whereby a calling party may operate said switches and code mechanism over any one of said telephone lines to effect a desired code of signals corresponding to any called one of a plurality of parties, and specific visual signals for con-

stantly indicating the call being made and the party being called thereby.

65. In a code call system, an automatic switch, lines, means whereby a calling party on any said line may operate said switch 70 over the corresponding line to effect a desired code of signals corresponding to any called one of a plurality of parties, and visual signals specific to the various codes of signals which will constantly indicate the 75 code call being made during the effectuation of the code.

66. In a code call system, an automatic switch, a line, means whereby a calling party on said line may operate said switch over the 80 line to effect a desired code of signals corresponding to any called one of a plurality of parties, and visual signals specific to the various codes of signals which will constantly indicate the code call being made during 85 the effectuation of the code.

67. In an automatic telephone system, a calling line, a subscriber's telephone on the near end of said line, a switch-hook of the telephone for initiating a call responsive to 90 removing the receiver of the telephone, a first selective switch at the far end of said line, a second selective switch accessible from said first switch, a called line accessible from said second switch, means for automatically operating said first and second switches from their restored positions over the calling line only after first removing the receiver from the switch-hook to extend a connection from the calling line to the called line, a manual switch on the called line for responding to 95 said connection, and means whereby said receiver may be replaced only before a response occurs on the called line without restoring one of said switches.

68. In an automatic telephone system, a calling line, a subscribers' telephone on the near end of said line, a switch-hook of the telephone for initiating a call responsive to removing the receiver of the telephone, a first selective switch at the far end of said line, a second selective switch accessible from said first switch, a called line accessible from said second switch, means for automatically operating said first and second switches from their restored positions over the calling line only after first removing the receiver from the switch-hook to extend a connection from the calling line to the called line, a manual switch on the called line for responding to said connection, means whereby said receiver may be replaced only before a response occurs on the called line without restoring one of said switches, and means responsive to thereafter again removing said receiver for thereby causing the switches to 100 restore to normal position.

69. In an automatic telephone system, a calling line, a subscriber's telephone on the near end of said line, a switch-hook of the 105

- telephone for initiating a call responsive to removing the receiver of the telephone, a selective switch, a called line accessible from said switch, means for directing the operation of said switch from its restored position over the calling line only after first removing the receiver from the switch-hook to extend a connection from the calling line to the called line, a manual switch on the called line for responding to said connection, and means whereby said receiver may be replaced only before a response occurs on the called line without restoring said switch.
70. In an automatic telephone system, a calling line, a subscriber's telephone on the near end of said line, a switch-hook of the telephone for initiating a call responsive to removing the receiver of the telephone, a selective switch, a called line accessible from said switch, means for directing the operation of said switch from its restored position over the calling line only after first removing the receiver from the switch-hook to extend a connection from the calling line to the called line, a manual switch on the called line for responding to said connection, means whereby said receiver may be replaced only before a response occurs on the called line without restoring said switch, and means responsive to thereafter again removing said receiver for thereby causing the switches to restore to normal position.
71. In a telephone system, a calling line, a subscriber's telephone on the near end of said line, a first selective switch at the far end of said line, a second selective switch accessible from said first switch, a called line accessible from said second switch, means operated for initiating a call on the calling line, means only thereafter operative for directing the selective operation of the switches to complete a connection from the calling line to the called line, manually operated means on the called line for responding to the connection from the calling line, and means whereby first said means may be restored without effacing the extension only after the called line has been selected.
72. In a telephone system, a calling line, a subscriber's telephone on the near end of said line, a first selective switch at the far end of said line, a second selective switch accessible from said first switch, a called line accessible from said second switch, means operated for initiating a call on the calling line, means only thereafter operative for directing the selective operation of the switches to complete a connection from the calling line to the called line, manually operated means on the called line for responding to the connection from the calling line, means whereby first said means may be restored without effacing the extension only after the called line has been selected.
73. In a telephone system, a calling line, a subscriber's telephone on the near end of said line, a selective switch at the far end of said line, a called line accessible from said switch, means operated for initiating a call on the calling line, means only thereafter operative for directing the selective operation of the switch to complete a connection from the calling line to the called line, manually operated means on the called line for responding to the connection from the calling line, and means whereby first said means may be restored without effacing the extension only after the called line has been selected.
74. In a telephone system, a calling line, a subscriber's telephone on the near end of said line, a selective switch at the far end of said line, a called line accessible from said switch, means operated for initiating a call on the calling line, means only thereafter operative for directing the selective operation of the switch to complete a connection from the calling line to the called line, manually operated means on the called line for responding to the connection from the calling line, and means whereby first said means may be restored without effacing the extension only after the called line has been selected.
75. In a code call system, automatic telephone apparatus, a line permanently independent of the talking conductors of the telephone apparatus, means controlled from a telephone of said apparatus to set said call system to effect a desired code of signals on said line to operate a signal device connected thereto, and means to indicate the signals being effected to the calling party over talking conductors of said telephone apparatus through his telephone receiver.
76. In a code call system, automatic telephone apparatus, means including said apparatus controlled from a telephone of said apparatus for causing a plurality of codes of audible signals to be sent, means whereby the party effecting the control from the telephone may terminate the signals, and means whereby the termination will only become effective at the termination of the specific code being sent when said termination operation is effected.
77. In a code call system, automatic telephone apparatus, means including said apparatus controlled from a telephone of said apparatus for causing a plurality of codes of audible signals to be sent, means whereby the party effecting the control from the telephone may terminate the signals, and means whereby the termination will only become effective at the termination of the specific code being sent when said termination operation is effected.

effective at the termination of a specific number of rounds of code signals after said terminating operation is effected.

78. In a code call system, automatic telephone apparatus, mechanism for an operator to manually set the code apparatus of the system to send any desired one of a plurality of codes, means including said telephone apparatus for automatically directing the setting of any desired one of said codes over a subscriber's telephone line of said apparatus, an operator's answering circuit, means for a party to respond to the code sent, and means depending upon what said means was used in setting the code call system to effect the code will determine if the party responding in a sole predetermined manner thereby directs a connection from his telephone to the operator's answering circuit or to the telephone of the subscriber effecting the call.

79. In a code call system, a code sending device, means for setting the code sending device to send successive rounds of codes of signals at will, and means for audibly indicating by a specific ending when a round is terminated.

80. In a code call system, a code sending device, means for setting the code sending device to send successive rounds of codes of signals at will, and means for audibly indicating by specific auxiliary signal when the round is terminated.

81. In a code call system, a code sending device, means for setting the code sending device to send successive rounds of codes of signals at will, and means for indicating by signal that the next signal will be the first signal of a code.

82. In a code call system, automatic telephone apparatus, means for manually setting the code apparatus of the system to send any desired one of a plurality of codes, means including a portion of said telephone apparatus for automatically directing the setting of any desired one of said codes, means including a portion of said telephone apparatus for making a response to the call by automatically calling a specific telephone number, and means depending upon whether the call was set manually or automatically for determining what operation will result from the response.

83. In an automatic telephone system, a signal sending apparatus, a called line, a plurality of means for causing the operation of said signal sending apparatus to cause like signaling upon said line irrespective of the said means operated, automatic means for responding to said signaling in like manner, and means dependent upon which means was used in causing the signaling will determine what operation will result from said response.

84. In a code call system, automatic tele-

phone apparatus including telephone lines, means for directing the operation of the code call system over a said telephone line to effect a code call, means for responding to said call over a second said telephone line and thereby establishing a talking connection to said first said telephone line from said second telephone line, and means for again operating the code call system from a third one of said telephone lines while first said connection remains established.

85. In a telephone system, a code call apparatus, a calling line, a signal device on the calling line, a code circuit, a signal device on the code circuit, means whereby the party on the calling line can operate his telephone to select the code circuit and to operate the signal device on the code circuit, means whereby the party called by the signal can respond by operating one of the telephones of the system as a responding telephone to select a predetermined number common to a plurality of mutually independent responding telephones to thereby connect with the specific calling line from which the signal is operated, means whereby the calling party can restore his telephone to normal idle position before last said connection is established without disconnecting from the code circuit, and means whereby the calling signal of the specific calling line from which the signal was operated will be operated responsive to last said connection being established.

86. In a telephone system, a code call apparatus, a calling line, a signal device on the calling line, a code circuit, a signal device on the code circuit, means whereby the party on the calling line can operate his telephone to select the code circuit and to operate the signal device on the code circuit, means whereby the party called by the signal can respond by operating one of the telephones of the system as a responding telephone to select a predetermined number common to a plurality of mutually independent responding telephones to thereby connect with the specific calling line from which the signal is operated, means whereby the calling party can restore his telephone to normal idle position before last said connection is established without disconnecting from the code circuit, means whereby the calling signal of the specific calling line from which the signal was operated will be operated responsive to last said connection being established without disconnecting from the code circuit, means whereby the calling signal of the specific calling line from which the signal was operated will be operated responsive to last said connection being established, and means whereby the party responding to the signal will receive indication that the calling party has restored his telephone and that the signal device on the calling line is being operated resultant to the last said party's response.

87. In a telephone system, a code call apparatus, a calling line, a signal device on the calling line, a code circuit, a signal de-

- vice on the code circuit, means whereby the party on the calling line can operate his telephone to select the code circuit and to operate the signal device on the code circuit, 5 means whereby the party called by the signal can respond by operating one of the telephones of the system as a responding telephone to select a predetermined number common to a plurality of mutually independent 10 responding telephones to thereby connect with the specific calling line from which the signal is operated, other means for connecting with the said calling line when in normal idle condition, and means whereby the calling line is now barred from connection 15 with except by calling said predetermined number.
88. In a telephone system, a calling line, a called line, a link including automatic switch mechanism for connecting the lines, means for maintaining a closed circuit path including a talking conductor of the calling line to maintain said connection established, means including a step-by-step timing device for destroying said connection only after the said device has made a plurality of step operations consequent to opening said path, and means whereby closing a circuit path of a talking conductor of the called line will disable said timing device for destroying the connection.
89. In a telephone system, a calling line, a called line, a link including automatic switch mechanism for connecting the lines, 35 means for maintaining a closed circuit path including a talking conductor of the calling line to maintain said connection established, means including a step-by-step timing device for destroying said connection only after the said device has made a plurality of step operations consequent to opening said path, means whereby closing a circuit path of a talking conductor of the called line will disable said timing device for destroying the connection, and means whereby again closing said path of the calling line will destroy the connection.
90. In a telephone system, a calling line, a called line, a link including automatic switch mechanism for connecting said lines, means for maintaining a closed path including a talking conductor of the calling line to maintain the connection established, and means whereby closing a circuit including a talking conductor of the called line after said closed path of the calling line is opened will disable the connection for being destroyed from the calling line because of said opening.
91. In a telephone system, a calling line, a called line, a link including automatic switch mechanism for connecting said lines, means for maintaining a closed path including a talking conductor of the calling line to maintain the connection established, and means whereby closing a circuit including a talking conductor of the called line after said closed path of the calling line is opened will disable the connection for being destroyed from the calling line because of said opening.
92. In a telephone system, a calling line, a called line, a link including automatic switch mechanism for connecting the calling and called lines, a line relay and a slow-restoring release relay of the link, means whereby responsive to both said relays becoming deactuated the connection will be destroyed, means whereby both said relays will be maintained actuated dependent upon a closed circuit path including a talking conductor of the calling line being maintained, means whereby said relays will deactivate responsive to opening said circuit path, means whereby the connection will remain established after both said relays have deactuated, and means whereby after both relays have deactuated while said connection exists a circuit closure including a talking conductor of the called line will prevent the connection being destroyed.
93. In a telephone system, a calling line, a called line, a link including automatic switch mechanism for connecting the calling and called lines, a line relay, the winding of a slow restoring relay in a local circuit of the line relay, means whereby responsive to both said relays becoming deactuated the connection will be destroyed, means whereby both said relays will be maintained actuated dependent upon a closed circuit path including a talking conductor of the calling line being maintained, means whereby said relays will deactivate responsive to opening said circuit path, means whereby the connection will remain established after both said relays have deactuated, and means whereby after both relays have deactuated while said connection exists a circuit closure including a talking conductor of the called line will prevent the connection being destroyed.
94. In a telephone system, a calling line, automatic switch mechanism, a calling signal device on the calling line, signaling current of two characters, means whereby the signaling device will be differently affected depending upon which signaling current source is applied to it, a called line, means including the switch mechanism for extending a call from the calling line to the called line, means whereby the calling line may be called as a called line, means for applying signaling current to the calling line consequent to the party on the called line responding by manually manipulating a cir-

cuit changer, and means whereby the source of signaling current applied to said signal device will be determined by whether the calling line is extending a call when signaling current is applied thereto or whether the calling line is being called.

95. In a telephone system, a telephone line, two branches of said line, a plurality of sets of connecting terminals on each said branch, switch mechanism for extending connection to the line through the respective sets of terminals of the branches, means controlled over said line for barring connection to the line through terminal sets of one said branch, and means controlled only from said mechanism after extending a said connection for barring further connection to the terminal sets of the other said branch.

96. In a telephone system, a telephone line, two branches of said line, a set of connecting terminals on each said branch, switch mechanism for extending connection to the line through the respective sets of terminals of the branches, means controlled over said line for barring connection to the line over one said branch, and means controlled from said mechanism after extending a connection for barring further connection to the line over the other said branch.

97. In an automatic telephone system, a directive switch, a line leading-in to the switch, an impulse sending device on the line for directing the operation of the switch in correspondence with the value of the series of impulses sent by said impulse sending device, a tone source, and means for applying the tone source audible on the line to indicate that the switch is responding to a series of impulses from said sending device before all the impulses of the series have been sent.

98. In an automatic telephone system, a directive switch, a relay for controlling the operation of the switch, a source of current, a leading-in line for the switch, a device for sending impulses when operated to direct the operation of the switch, the winding of the relay and source of current and leading-in line and said device being in a series circuit path, a tone source, and means whereby when the directive device is operated the tone source will be applied audible in the telephone to indicate that the relay has operated.

99. In an automatic telephone system, a directive switch, a relay for controlling the operation of the switch, a source of current, a leading-in line for the switch, a device for sending impulses when operated to direct the operation of the switch, the winding of the relay and source of current and leading-in line and said device being in a series circuit path, a tone source, and means whereby when the directive device is operated the

tone source will be applied audible in the telephone upon the circuit becoming closed to indicate that the relay has operated.

100. In an automatic telephone system, a directive switch, a relay for controlling the operation of the switch, a source of current, a leading-in line for the switch, a device for sending impulses when operated to direct the operation of the switch, the winding of the relay and source of current and leading-in line and said device being in a series circuit path, a tone source, and means whereby when the directive device is operated the tone source will be applied audible in the telephone to indicate that the relay has operated regardless of any movement of the switch.

101. In a telephone system, an automatic switch, means for operating the switch from its normal idle position, a release magnet for restoring the switch to its normal position upon being operated, a called line, fixed terminals of the called line, movable terminals of the switch for connecting with the called line, a timing device for limiting the duration through which the movable terminals may remain connected with the first terminals, and means including the timing device for operating the release magnet to thereby restore the switch to its normal position.

102. In a telephone system, an automatic switch, means for operating the switch from its normal idle position, a release magnet for restoring the switch to its normal position upon being operated, a called line, fixed terminals of the called line, movable terminals of the switch for connecting with the called line, a timing device for limiting the duration through which the movable terminals may remain connected with the first terminals, and means including the timing device and a said movable terminal for operating the release magnet to thereby restore the switch to its normal position.

103. In a telephone system, automatic switch mechanism, a calling device, a calling line, means including the calling device for directly operating the switch mechanism over the calling line, means on the calling line for directly restoring the switch mechanism to normal idle position over the calling line, a timing device, and automatic means including the timing device whereby if the switch mechanism does not forthwith restore responsive to second said means the switch will thereafter be restored at the expiration of a predetermined time.

104. In a telephone system, automatic switch mechanism, a calling device, a calling line, means including the calling device for directly operating the switch mechanism over the calling line, means on the calling

line for directively restoring the switch mechanism to normal idle position over the calling line, a timing device common to a plurality of said switch mechanisms but operative with but a single said switch mechanism at any time, and automatic means including the timing device whereby if the switch mechanism does not forthwith

restore responsive to second said means the switch will thereafter be restored at the 10 expiration of a predetermined time.

In witness whereof, I hereunto subscribe my name this 18th day of January, A. D. 1921.

HERBERT M. FRIENDLY.
